UNITED STATES PATENT OFFICE

FRANK CARTLIDGE, OF CLAREMONT, NEW HAMPSHIRE, ASSIGNOR TO SULLIVAN MACHINERY COMPANY, A CORPORATION OF MASSACHUSETTS

MINING MACHINE

Application filed January 7, 1918, Serial No. 210,696. Renewed February 4, 1927.

My invention relates to mining machines.

My invention has for its object to provide an improved machine adapted to use at will to insert either a vertical or a horizontal cut in the face of an entry. A further object of 5 my invention is to produce an improved machine of this character which may be transported from place to place upon a suitable truck, and maintained upon that truck during the several cutting operations. A still 10 further object of my invention is to provide an improved machine wherein the cutting mechanism may be fed or adjusted expeditiously and with great facility into the desired relations with respect to the face, either 15 when undercutting or shear cutting, the means for adjusting the machine preferably being power operated. Another object of my invention is to provide an improved machine adapted to use as an undercutter, which is also 20 provided with improved means whereby the bottom of the entry may be maintained at the desired level without supplemental shooting, etc., or whereby the undercut may be inserted 25 upon widely different levels or inclinations relative to the track. A still further object of my invention is to provide an improved machine 30 of the character set forth which is especially adapted to use in the cutting of room necks leading from the entry, or to use as a track mounted longwall machine, all as 35 conditions may require. A still further object of my invention is to provide a machine of improved and simplified construction which, while of a rugged character and well 40 adapted to withstand the hard usage to which such machines are subjected in service, is also of such construction that it may be very readily and cheaply manufactured and conveniently transported from place to place and 45 adjusted into its several position with great facility and dispatch. These and other objects of my invention will, however, herein after more fully appear.

45 In the accompanying drawings, I have shown one embodiment which my invention may assume in practice. It will be understood, however, that this form of my improvement is used only for purposes of illustration 50 and that the invention itself may be modified

and embodied in various other forms without departing from its spirit.

In the drawings of this illustrative embodiment,—

Fig. 1 is a plan view of the improved machine when adjusted for undercutting and in transport position, certain parts of the mechanism being broken away to facilitate illustration. 55

Fig. 2 is a side elevation of the machine 60 when in the same position, certain parts of the mechanism here being omitted or broken away to facilitate illustration.

Fig. 3 is a plan view of the machine, similar to Fig. 1, but showing the machine ad- 65 justed for shearing, certain parts herein also being omitted to facilitate illustration.

Fig. 4 is a side elevation of the machine 70 when the same is in the position shown in Fig. 3.

Fig. 5 is a detail partial sectional view 75 taken substantially on line 5—5 of Fig. 1.

Fig. 6 is a rear elevation, partially in section, of the machine shown in Fig. 1.

Fig. 7 is an enlarged detail view of the 75 track operating mechanism shown in Figs. 1 and 3.

Fig. 8 is an enlarged detail view, partially 80 in section, taken substantially on line 8—8 of Fig. 1.

Fig. 9 is an enlarged detail view, partially 85 in section, taken substantially on line 9—9 of Fig. 2.

Fig. 10 is an enlarged detail end elevation, 90 partially in section, showing the slide adjusting means.

Fig. 11 is a similarly enlarged side elevation showing this mechanism.

Fig. 12 is a simplified diagrammatic plan view of the machine when adjusted for shear- 95 ing and in transport position in an entry.

Fig. 13 is a simplified diagrammatic side elevation showing the cutter bar in position to make its shearing cut.

Fig. 14 is a similar view showing the cutter 95 bar at the completion of its initial shearing cut.

Fig. 15 is a similar view showing the cutter bar at the completion of its second or vertical swinging cut. 100

Fig. 16 is a similar view showing the cutter bar at the completion of its third or withdrawal cut.

Fig. 17 is a simplified diagrammatic plan view showing the machine adjusted to insert a shear cut in a face located parallel to the track.

Fig. 18 is a similar view showing the machine with its cutter bar adjusted to insert a shear cut at a different point in the entry face.

Fig. 19 is a similar view showing the machine with its cutter bar in position to begin the first cut of the undercutting operation.

Fig. 20 is a similar view showing the cutter bar at the completion of this first cut.

Fig. 21 is a similar view showing the cutter bar at the completion of its second or transverse swinging cut.

Fig. 22 is a similar view showing the cutter bar after its third or withdrawal cut.

Fig. 23 is a similar view showing the machine adjusted to insert an undercut in a face parallel to the track.

Fig. 24 is a similar view showing the cutter bar adjusted in a plurality of positions used in cutting room necks.

Fig. 25 is a similar view showing the cutter bar at the completion of its initial cut when cutting a room neck.

Fig. 26 is a similar view showing the cutter bar in process of widening the room neck, or in use as on a mounted longwall machine.

Fig. 27 is a simplified diagrammatic side elevation of the machine when undercutting, the same showing the cutter bar so inclined downwardly as to maintain the bottom and cut beneath the level of the rails.

Fig. 28 is a similar view showing the cutter bar disposed in another cutting position, the same therein being shown to be inclined upwardly with respect to the rails in such a manner as to cut above the same.

Fig. 29 is a simplified diagrammatic end elevation of the machine with its cutter bar adapted to cut an undercut at a downward angle at the side of the machine and relative to the track.

Fig. 30 is a similar view showing the cutter bar adjusted into another position relative to the track.

In this illustrative construction, I have shown a truck mounted machine equipped with a cutter bar and an endless cutter chain of the type now ordinarily in use in coal cutting machines, and provided with improved means whereby the said cutter bar may be adjusted into various operative positions to insert an undercut or to cut a vertical kerf, all while the same is maintained upon the truck, and preferably through the provision of power operated mechanism adapted to enable the several adjustments to be made very quickly and with great facility.

Referring more particularly to the drawings, (Figs. 1 and 2) it will be noted that

the machine includes a truck frame 1 mounted on wheels 2 which are in turn adapted to run upon the usual track rails 3. As illustrated, this truck 1 is preferably adapted to be propelled about the mine under its own power, the same herein being shown as having its wheels connected, as through a chain and sprocket connection 4, and driven through a chain and sprocket connection 5 from a rotating power shaft 6 disposed at the rear end of the truck and operatively connected, as for instance to the armature shaft of a suitable motor 7. In a preferred form, this motor 7 is of the reversible type and carried beneath the truck and controlled by a suitable controller 8 having a handle 9 which is in turn adapted to be provided, at will, with a suitable extension 10 accessible from the top of the elements carried by the truck and hereinafter described. Thus, it will be noted that the truck may be propelled about the mine under its own power and controlled through suitable manipulation of the controller handle 9.

Carried upon this truck frame 1 and disposed over the same is a supplemental supporting frame 11, herein shown to be normally disposed in a plane parallel to the plane of the track and the truck frame 1, and disposed a slight distance above the latter. As shown in Fig. 2, this supporting frame is provided at its front end with depending portions 12 pivoted at 13 on the front end of the truck frame 1, and is provided at its rear end with suitable means for adjusting the same vertically about this pivot. These means may, obviously assume various forms. However, in the form of my invention shown, it will be noted that the same are power operated and include (Figs. 10 and 11) a vertically disposed, two-part, pivotally connected screw 14 extending through an aperture approximately in the center of the rear end of the truck frame 1 and adjustable in a suitable nut 15 which is in turn journaled in a depending bracket 16 on the frame 1. As shown, this screw 14 has its upper end pivotally connected at 17 to the rear end of the support 11, the construction being such that the support 11 is raised about its pivot 13 when the nut is rotated in one direction and is lowered about that pivot when the nut is rotated in the opposite direction. As shown, the nut 15 is in the form of a sprocket and is held in place by a removable cover plate 18 and connected through a power connection 19 including a chain and a corresponding sprocket fixed on a vertically disposed rotating shaft 20, suitably journaled on the motor frame. In the form of my invention illustrated, this shaft 20 carries on its upper end a worm wheel 21, which in turn meshes with a worm 22 carried on the transverse or motor shaft 6 and operatively connectible therewith at will through a suitable

adjustable clutch mechanism 23. Thus, it will be observed that when desired, through a suitable manipulation of the clutch mechanism 23 and the controller handle 9, power may be supplied from the motor 7 to raise or lower the support 11 relative to the truck frame 1 or the support may be held in various tilted positions. It will also be observed that in order that this adjustment may take place while the truck is at rest, I have also provided suitable adjustable clutches 24 on the ends of the shaft 6, by means of which the truck driving mechanism may, obviously, be disconnected from the motor and the latter thereafter operated in one direction or reversed when it may be necessary in adjusting the support 11.

As shown in Figs. 1 and 2, it will be noted that the support 11 carries a suitable plate 25 which is centrally swiveled thereon at 26 and is likewise horizontally disposed and adapted to act as a support. As shown, this plate has rigidly connected to it, as by means of suitable bracing and supporting means 27 and 28, a suitable upstanding, elongated and longitudinally extending guiding and feeding frame 29, preferably comprising a plurality of parallel longitudinally disposed frame members 30 rigidly connected by a transverse plate 31 in such a manner as to form a rigid structure relative to which the mining machine, hereinafter described, and its operating motor 32 which is of the usual reversible type, may be adjusted longitudinally. As shown in Fig. 6, the motor 32 of the mining machine is disposed longitudinally of the frame and mounted on a suitable supporting plate 33 which is itself adapted to be slid bodily along suitable guideways 34 formed on the supporting and guiding frame 29. Obviously, the motor and its frame 33 may be thus adjusted in various ways. In a preferred form, however, the power necessary to make this adjustment is derived from the motor 32 and suitable transmission mechanism is provided whereby the motor may be adapted to feed the frame in either direction.

In the form of my invention shown, it will be observed (Fig. 6) that the rear end of the armature shaft 35 carries a beveled gear 36 constantly meshing with a plurality of oppositely disposed beveled gears 37 and 38, which are in turn carried on a suitable transverse shaft 39 journaled in bearings 40, connected to the motor frame or the member 33, and freely rotatable at will with either of the gears 37 and 38, depending upon the position of an adjustable clutch mechanism 41. (See Fig. 2.) As shown, this shaft 39 is vertically disposed and provided at its upper end with a worm 42 meshing with a suitable worm gear 43. As illustrated, this worm gear 43 is carried upon a horizontally and longitudinally disposed shaft 44 journaled on the support 33 and carrying on its opposite

end a worm 45 meshing with a worm gear 46. This worm gear 46 is in turn carried on a horizontally and transversely disposed shaft 47, likewise journaled on the support and having on its opposite extremity a worm 48 meshing with a worm gear 49 carried on a transverse shaft 50. As shown in Fig. 7, this transverse shaft 50 carries pinions 51 on its opposite ends, which in turn mesh with rack surfaces 52 formed on the members 30. Thus, it will be observed that the rotation of the armature shaft 35 of the motor 32 may be transmitted in such a manner as to cause the motor 32 to be fed bodily relative to the supporting and guiding frame 30, 31, and that through manipulation of the clutch mechanism including the clutch lever 41, the motor may be fed in either direction or disconnected in such a manner as to remain stationary in any given position. Obviously, the movement of the motor may also be controlled through the action of a suitable controller 53, which is of a type similar to the controller 8 and is in turn controlled through manipulation of a suitable controller handle 54.

Operatively connected to the motor 32 and bodily movable therewith relative to the supporting and guiding means 30, 31, is the cutting mechanism. As shown in Figs. 1 and 2, this cutting mechanism includes a cutter bar 55 carrying the usual endless cutter chain 56, which is in turn equipped with the usual cutter bits 57 and adapted to be actuated by the rotation of a suitable chain driving sprocket 58. In the form of my invention shown, this chain driving sprocket is connected to the front end of the armature shaft 35 through beveled gears 59 and 60 of which the latter is connected directly to the sprocket through a suitable shaft 61, which is in turn vertically disposed in a suitable bracket or head 62, preferably swiveled on the front end of the motor shaft. As shown, a clutch 63 is herein also provided between this shaft 61 and the chain driving sprocket 58 in such a manner that the cutter chain may be disconnected at will from the driving motor 32, as for instance when the latter is utilized to drive the feeding mechanism. However, it will be clearly apparent that when desired this clutch 63 may be connected at the same time that the motor 32 is operated, in such a manner that the cutter chain will be caused to rotate and cut the coal simultaneously with the forward feeding movement of the cutter chain and motor relative to the supporting and guiding elements 30, 31.

In my improvement, means are also provided whereby the cutter bar 55 may be adjusted angularly about the shaft 61 as an axis. For this purpose, it will be noted that the cutter bar 55 is provided with a bracket 64 (Figs. 1 and 2) which is journaled on the lower end of the shaft 61, and is also equipped with an arcuate rack 65 meshing with a pinion 130

66. As shown in Figs. 1 and 3, this pinion 66 is carried on the lower end of a vertical shaft 67 journaled in a suitable extension on the bracket 62 and carrying on its upper end a worm gear 68. This worm gear 68 in turn meshes with a worm 69 carried on the front end of a longitudinally disposed shaft 70, likewise journaled on the bracket 62, and which in turn carries at its opposite end a worm gear 71 meshing with a vertically disposed worm 72 carried on the upper end of the shaft 61 and connectable at will therewith when a suitable clutch 73 is operated. Thus, it will be observed that the cutter bar 55 may be swung about the shaft 61 as an axis to vary its angle relative to the face or the material to be cut, through a simple movement of the clutch 73 from its neutral position, the direction of swing of the bar being determined by the direction of rotation of the motor 32.

In order that the bar 55 may be adjusted in such a manner as to vary the angle of the cut as desired, I have also provided improved means whereby the bar may be adjusted bodily about a longitudinal axis. These means, as shown in Figs. 5 and 8, include means whereby the bracket 62 may be swung bodily about the axis of the armature shaft 35 and comprise a worm gear 74, meshing with another suitable worm 75 upon the shaft 61, and in turn carried on a transverse shaft 76 journaled in the bracket 62. As shown, this shaft 76 also carries on its opposite end a worm 77 meshing with a worm wheel 78 carried on the front end of a longitudinally disposed shaft 79 likewise journaled in the bracket 62, and this shaft 79 carries on its rear end a pinion 80 (Fig. 5) meshing with a curved or arcuate rack 81 carried by the longitudinally adjustable motor frame 33. In order to control the connection of these parts and to permit this adjustment to be made at any desired time, I have also provided the clutch 73 with a second set of teeth in order that it may control the connection of the shaft 79 to the rotating shaft 61. Thus, it will be observed that whenever it is desired to swing the cutter bar either from a horizontal to a vertical position to make a shear cut, or from a vertical to a horizontal position to make an over or under cut, or to any of the various intermediate positions, the same may be readily accomplished through a simple manipulation of this clutch 73 and control of the motor 32 in such a manner as to transmit the power in the proper direction to the pinion 80, and thereby cause the entire bar and the swivel head including the bracket 62, to be moved from one position to the other. In the foregoing description there has been provided a general description of structural features of my invention, details which will be obvious to any one skilled in the art being omitted so far as possible to avoid unnecessary length.

In the operation of my improved construction, let us first consider the making of a vertical or shear cut, and refer particularly to Figs. 12 to 18, inclusive. In these figures, it will be noted that the machine above described is illustrated diagrammatically and in simplified form in such a manner as to bring out more clearly the various positions of the cutter bar relative to the machine and to the work. For instance, in Fig. 12 the machine is shown in its transport position in the entry prior to the first step of the shearing operation. In this position it will be observed that the cutter bar is disposed vertically at the side of the machine, and that due to the fact that the tracks 3 are usually laid at one side of the entry, the bar 55 is thus brought substantially in line with the center line of the entry. As a first step in the shearing operation, a jack 83 (Fig. 1), preferably normally swiveled on the part 30 of the frame 30, 31 near the front end of that frame, is preferably swung from the longitudinally disposed position shown in Figs. 1 and 12 to the vertically disposed position shown in Fig. 13. In this position, the jack 83 is suitably fixed to the roof and bottom in a well known manner by means of its adjusting portions 84. Thus, it will be observed that a very rigid support is produced, the jack cooperating with the wheels 2 to support the cutting mechanism. After the jack has been thus set and the various other clutches disconnected, the clutch 73 is then operated in such a manner as to transmit rotation from the motor 32 whose rotation in the proper direction is effected by operation of the controller 53, through the transmission mechanism above described, to the pinion 66 and thereby cause the rack 65 and the cutter bar 55, which is connected thereto, to be moved upward from the position shown in Fig. 4 to the position shown in Fig. 13. In this position, the clutch 73 is then disconnected and the bar is then in position to be inserted upon reversal of the motor 32 in the coal through a suitable manipulation of the clutch lever 41 in such a direction as to cause the pinions 51 to be rotated to feed the entire motor and its connected mechanism forward upon the racks 52 from the position shown in Fig. 4 to the position shown in Fig. 13. Thereupon, the clutch controlling the connection of the cutter chain driving sprocket is also actuated in such a manner as to connect the sprocket to the motor, and the bar is thereafter fed further forward and into the coal with its cutter chain rotating in such a manner as to cut out a kerf of substantially the shape shown in Fig. 14. When this position is reached, the clutch controlling member 41 is thrown into neutral position in such a manner as to arrest the forward movement of the cutting mechanism, and the clutch 73 is again actuated, this time, however, in a reverse di-

rection to effect its connection again, in such a manner as to cause the bar 55 to be swung downward from the position shown in Fig. 14 to the position shown in Fig. 15, so that, as 5 the cutter chain continues to rotate during the swinging movement, an arcuate kerf is cut until the parts occupy the position shown in Fig. 15. When this position is reached, the clutch 73 is again actuated to disconnect the 10 mechanism for angling the bar, and the clutch controlling member 41 is actuated reversely in such a manner as to cause the cutting mechanism to be fed rearward relative to the rack 52 and thereby, as the cutter chain 15 continues to rotate, cut out the remaining uncut portion of the kerf shown in Fig. 15, the operation continuing until the parts occupy the position shown in Fig. 16. When in this position and after a reversal of the 20 motor, obviously if desired, by a simple further operation of the clutch 73 to throw it in, the bar may be returned to its normal or transport position shown in Fig. 4 and the machine transported on its truck to another 25 entry, the movement of the truck then being controlled by the controller handle 9, 10.

In the use of my improved machine as a shearer, it may, however, be desirable to cut a vertical kerf in the side wall of an entry, as 30 for instance in starting a room neck. When it is desired to cut such a kerf, it is only necessary to remove the extension 10 of the controller handle and swing the entire mechanism about on the swivel member 25 from 35 the transport position shown in Fig. 12 to the position shown in Fig. 17, and thereafter fix the jack 83 in engagement with the roof and bottom, whereupon the entire cutting mechanism may be operated to insert a series 40 of kerfs such as above described, in the side of the entry. Moreover, through the use of this swivel mounting, it is also possible to adapt the machine to cutting a vertical kerf in an effective manner, even although the 45 tracks are not laid at the left hand side of the entry as shown in Fig. 12. For instance, the track rails may be laid at the right hand side of the entry, as shown in Fig. 18, in which case, with the bar disposed at the right hand 50 side of the machine, as shown in Fig. 12, the kerf would be cut at a point too closely adjacent the right hand rib. However, through the use of my improved swivel mechanism, it will be noted that the entire cutting mechanism 55 may be turned about this swivel in such a manner as to bring the end of the cutter bar more closely adjacent the center line of the entry and thus enable the end of the same at the completion of the shearing cut to lie in 60 the center of the entry, or to intersect the center line of the entry in such a manner as to insure better results from shooting the coal. Obviously, through the provision of this 65 swivel mechanism, a shear cut may also be inserted at practically any point in either

rib of an entry or room or in a face substantially parallel to the track, by simply rotating the cutting mechanism into any desired angular position relative to the truck.

In the use of my improved construction in undercutting, substantially the same mechanisms are employed, and the cut is made in substantially the same manner. However, it will be observed that it is necessary for the cutter bar to be adjusted from the vertical 70 position for making a shear cut to the horizontal position necessary to an undercut. This adjustment is readily accomplished through the utilization of the swivel mounting of the cutter bar relative to the front end 75 of the armature shaft of the motor, it being possible to swing the entire frame 62 and the cutter bar from one position to another whenever desired by simply adjusting the clutch controlling the connection of the pinion 80 when the motor 32 is operating in the desired direction. For instance, with the cutter bar in its vertical or shearing position shown in Fig. 3, it is only necessary to adjust this clutch 85 and properly control the motor in order to swing the bar from that vertical position to the horizontal position desired in undercutting and shown, for instance, in Fig. 2. When the parts are in this position, it will be 90 obvious that, the motor 32 being reversed 95 from its direction of rotation during the downward swing, through the actuation of the swinging mechanism for the bar, above described, the latter may be adjusted angularly into the position shown in Figure 19 in 100 readiness to make its sumping or starting cut. Thereafter, the motor 32 being again reversed 105 it will also be evident that in order to reciprocate the bar to make this cut, the clutch 63 controlling the cutter chain is next operated, as well as the clutch controlling member 41, 110 in such a manner as to cause the bar to move into the coal while its cutter chain is rotating, to produce the cut shown in Fig. 20. When the cutter bar reaches the position shown in 115 that figure, the clutch 41 is again operated in such a manner as to disconnect the forward feed of the machine, and the clutch controlling the swinging mechanism for the bar is again operated to swing the bar from the 120 position shown in Fig. 20 to the position shown in Fig. 21. When this position is reached, the swinging mechanism is again disconnected and the clutch controlling member 41 is again operated, but in a reverse direction, in such a manner as to withdraw the cutting mechanism from the position shown in Fig. 20 to the position shown in Fig. 22, and thereby complete the cut.

In the use of my improved mechanism as an undercutter, it will also be evident that, as above described in connection with the use of the same as a shearer, the entire mechanism may be swung at right angles to the track, as shown in Fig. 23, and the jack 83 125

set in such a manner as to enable the machine to insert an undercut in either the rib of an entry or room, or in any face disposed substantially parallel to the track. As shown in Figs. 24 to 26, inclusive, it will also be evident that the mechanism may be used to cut out a room neck at either side of the machine, the cutter chain and forward feeding mechanism then being operated simultaneously in such a manner as to swing the bar toward the desired rib at the same time that the bar is fed forward. As a result of this movement, obviously, an inward cut of practically any desired curvature may be produced, or the bar may be inserted as shown in Fig. 25, substantially at right angles to the track so that by simply reciprocating the machine rearward along the track, an undercut of sufficient length to form the room neck may be produced. Obviously, if desired, the bar may also be thus inserted at either side of the machine and an undercut after the nature of a longwall cut may be produced, the machine then constituting substantially a mounted longwall machine. It will also be evident that by the provision of any suitable means, as, for instance, the registering perforations 85 in the plate 11 and the plate 25, and a co-operating pin 86, the parts may be held in any desired position of adjustment.

In the use of my improved construction, an advantage of considerable importance when undercutting is obtained through the use of the means for adjusting the level of the platform 11, as by so doing it is possible to maintain the bottom by cutting substantially on the same, and thus eliminate any necessity for shooting the uncut coal ordinarily left between the top of the rails and the mine bottom by most machines. This is readily accomplished in my improved construction, as shown in Fig. 27, by simply elevating the rear end of the platform 11 and thereby bringing the front end of the bar substantially into contact with the mine bottom prior to the beginning of the undercut, so that when the machine is advanced bodily relative to the supporting and guiding frame 30, 31, the bar is caused to cut slightly downward and into the coal which would remain uncut when the bar was operated only on a level above the level of the track. Through a reverse operation of this means, it is also evident, as shown in Fig. 28, that the front end of the bar may be raised where conditions require such an adjustment, in such a manner as to cut over an obstruction or on a pitching seam. Thus, through the provision of my improved adjusting means, it will be observed that a far wider range of adjustment of the cutter bar is made possible, and that not only is all necessity for a separate shooting of any coal underlying the kerf entirely obviated, but that it is made possible to adapt the machine to cutting in different conditions wherein it is

advisable for the outer end of the cutter bar to be slightly raised during the undercutting operation.

As shown in Figs. 29 and 30, it will also be observed that through the utilization of the swivel mounting for the cutting mechanism, whereby the latter may be adjusted relative to the front end of the armature shaft, it is also possible to vary the angle of the bar when the same is used to cut at the side of the machine, as for instance when the same is cutting as shown in Fig. 26, it only being necessary to throw in the clutch controlling the gear 80 and effect rotation of the motor in the desired direction in order to swing the cutter bar up or down, as desired. For instance, if it is desired to swing the bar downward, as when it is desired to cut a kerf at a downwardly sloping angle from the track, this may be readily accomplished, the parts 85 then assuming the position shown in Fig. 29; while when it is desired to cut a horizontal kerf and the bar is disposed at an angle, this is readily accomplished by adjusting the parts into the position shown in Fig. 30.

As a result of my improved construction, it will be noted that a machine is produced which is adapted to cut either a shear cut or a horizontal undercut or overcut, whenever desired, the machine thereby being adapted to cutting in those territories where only a shear cut is desired, and at the same time adapted to cutting in those territories wherein either an undercut or an overcut only is desired, or in those territories wherein, due to the character of the coal, it is desirable to insert both a shear cut and a horizontal cut of either type. It will also be observed that through the provision of my improved mechanism, it is possible to cut an undercut substantially upon the mine bottom, and to insert this undercut at any desired angle either up or down when the undercut is made in front of the machine, as in entry driving, or at the side of the machine when cutting a room neck, or when the machine is operated as a mounted longwall cutter. Through the provision of my improved adjusting means, it will be noted that each and every adjustment of the machine may, if desired, be made under the power of the machine, so that the adjustment may be made not only with great facility, but very quickly, in such a manner as to enable a large number of places to be cut in a shift. These and other advantages of my improved construction will, however, be clearly apparent to those skilled in the art.

In the appended claims the terms "longitudinal" and "transverse" are used, with reference to axes, in the sense of extending longitudinally of the machine as a whole, or transversely of the machine as a whole, unless otherwise plainly indicated in the claims themselves.

While I have in this application specifically

described one embodiment which my invention may assume in practice, it will be understood that this form of the same is used for purposes of illustration and that the invention may be modified and embodied in various other forms without departing from its spirit or the scope of the appended claims.

What I claim as new and desire to secure by Letters Patent is:

10. 1. In a mining machine, a support, cutting mechanism thereon including a swiveled cutter bar carrying a cutter chain, said bar being adjustable bodily into cutting position in a plurality of intersecting planes to position 15 the same for the cutting of kerfs intersecting in lines extending longitudinally of said support, a motor for operating said cutter chain, and means operable by said motor to effect said bodily movement of said bar to the desired plane and to swing said bar in any plane 20 to which it may be moved.
2. In a mining machine, a truck, longitudinally disposed guiding means swiveled thereon about an axis parallel to the plane 25 of said guiding means, cutting means movable longitudinally of said guiding means and including a motor and a pivoted cutter bar, and means whereby the pivot of said cutter bar may be bodily rotated by power 30 from said motor.
3. In a mining machine, a wheeled support, longitudinally extending guiding means thereon, a motor reciprocable between the ends of said guiding means, motor reciprocating means including a rack carried by said guiding means, and cutting mechanism operatively connected to said motor including a forwardly extending vertically disposed horizontally pivoted cutter bar.
40. 4. In a mining machine, longitudinally extending guiding means, a motor reciprocable relative to said guiding means and between the ends thereof, said motor having a power shaft disposed parallel to its path of reciprocation, motor reciprocating means including a power connection with said motor, cutting mechanism operatively connected to said motor including a forwardly extending vertically disposed horizontally pivoted cutter 45 bar, and means for swinging said bar about its pivot.
5. In a mining machine, a support, guiding means thereon, a motor reciprocable relative to said guiding means and between the ends thereof, cutting mechanism operatively connected to said motor and including a pivoted longitudinally extending bar, means operable by said motor for rotating the pivot of said bar about a longitudinally disposed 55 axis, and means for swinging said bar about its pivot.
6. In a mining machine, a support, substantially horizontally extending guiding means thereon, a motor reciprocable relative 60 to said guiding means and between the ends
- thereof, cutting mechanism operatively connected to said motor including a pivoted longitudinally extending bar, power operated means for rotating the pivot of said bar about a longitudinally disposed axis, and power operated means for swinging said bar about its pivot. 70
7. In a mining machine, a support, guiding means thereon, a motor reciprocable relative to said guiding means and between the ends thereof, cutting mechanism operatively connected to said motor and including a pivoted bar extending parallel to said guiding means, motor operated means for rotating the pivot of said bar about an axis disposed parallel to the direction of said guiding means, means for swinging said bar about its pivot, and motor operated mechanism for reciprocating said motor relative to said guiding means. 75
8. In a mining machine, a support, substantially horizontally extending guiding means thereon, a motor reciprocable relative to said guiding means and between the opposite ends thereof, cutting mechanism operatively connected to said motor and including a pivoted longitudinally extending bar, motor operated means for rotating the pivot of said bar about a longitudinally disposed axis, and means operated by said motor for 80 reciprocating said bar about its pivot. 85
9. In a mining machine, a support, guiding means thereon, a motor reciprocable relative to said guiding means, cutting mechanism operatively connected to said motor and including a longitudinally extending pivoted cutter bar, means operable by said motor for rotating said bar about a longitudinally disposed axis parallel to the plane of the bar, means for swinging said bar about its pivot, and means operated by the motor for reciprocating said motor relative to said guiding means. 90
10. 10. In a mining machine, a support, guiding means thereon, a motor reciprocable relative to said guiding means and between the ends thereof, cutting mechanism operatively connected to said motor and including a longitudinally extending pivoted cutter bar, power operated means for rotating said bar about a longitudinally disposed axis including a driving connection with said motor, power operated means for swinging said bar about its pivot, and power operated means for reciprocating said motor relative to said guiding means including mechanical driving connections between said motor and said guiding means. 100
11. 11. In a mining machine, a support, longitudinally extending guiding means thereon, a motor reciprocable in said guiding means and between the ends thereof, motor reciprocating means driven from said motor and including a motor rotated member and means traversed thereby in either direction 105
- 120
- 125
- 130

- carried by said guiding means, cutting mechanism operatively connected to said motor including a forwardly extending vertically disposed horizontally pivoted cutter bar, and power operated means for swinging said bar about its pivot.
12. In a mining machine, a support, longitudinally extending guiding means thereon, a motor reciprocable in said guiding means and between the ends thereof, cutting mechanism operatively connected to said motor including a forwardly extending vertically disposed horizontally pivoted cutter bar, power operated means for swinging said bar about its pivot, and power operated means for reciprocating said motor including cooperating interengaging stationary and rotatable means, one moving with said motor and the other carried by said guiding means.
13. In a mining machine, a support, longitudinally extending guiding means thereon, a motor reciprocable in said guiding means and between the ends thereof, cutting mechanism operatively connected to said motor including a forwardly extending vertically disposed horizontally pivoted cutter bar, means for swinging said bar about its pivot, means for reciprocating said motor including cooperating stationary and rotatable members carried by said motor and said guiding means, and self-contained means for reciprocating said support.
14. In a mining machine, a support, a platform thereon, cutting mechanism longitudinally movable relative to said platform and including a forwardly extending pivoted cutter bar, and means for adjusting said platform to vary the inclination of said bar relative to said support.
15. In a mining machine, a support, a platform thereon, cutting mechanism carried on said platform and rectilinearly reciprocable relative thereto and including a forwardly extending pivoted cutter bar, and power operated means for adjusting said platform to vary the inclination of said bar relative to said support.
16. In a mining machine, a support, a platform carried thereon, cutting mechanism rectilinearly reciprocably carried on said platform including a pivoted cutter bar, means for varying the elevation of one end of said platform to effect tilting thereof, and means for thereafter reciprocating said cutting mechanism relative thereto.
17. In a mining machine, a support, a platform pivoted to the front end thereof, rectilinearly reciprocable cutting mechanism carried on said platform including a pivoted cutter bar, means for elevating the rear end of said platform to effect tilting thereof, and means for thereafter reciprocating said cutting mechanism relative thereto.
18. In a mining machine, a wheeled support, a platform pivoted thereon, rectilinearly reciprocable cutting mechanism carried on said platform including a pivoted cutter bar, means for elevating one end of said platform to tilt the latter, means for thereafter reciprocating said cutting mechanism relative thereto, and means for thereafter swinging said cutter bar about its pivot.
19. In a mining machine, a support, an overlying platform pivotally connected thereto for tilting about a horizontal axis, cutting mechanism carried on said platform including a cutter chain carrying cutter bar pivotable about an axis within the orbit of the cutter chain, power operated means for propelling said support, and means operatively connected to said last mentioned means for varying the position of said platform.
20. In a mining machine, a support, an overlying platform pivotally connected to the front end thereof for tilting on a horizontal axis, cutting mechanism carried on said platform and including a frame swiveled thereon on a vertical axis and a motor rectilinearly reciprocable relative to said frame and a forwardly extending cutter bar normally disposed in a substantially horizontal plane, and means operating upon the rear end of said platform whereby the angle of said bar relative to the horizontal may be adjusted at will.
21. In a mining machine, a wheel mounted support, an overlying platform pivotally connected to the front end thereof, guiding means on said platform, cutting mechanism carried on said guiding means and rectilinearly reciprocable relative thereto and including a pivoted cutter bar, and power operated means operating upon the rear end of said platform whereby the elevation of the rear end of the latter is varied and the angle of said bar relative to the horizontal may be adjusted at will.
22. In a mining machine, a wheel-mounted support, a platform pivoted thereon on a horizontal axis, guiding means swiveled on a vertical axis on said platform, cutting mechanism longitudinally movable on said guiding means and including a pivoted cutter bar, and means operatively connected between said support and said platform for varying the position of the latter relative to said support.
23. In a mining machine, a wheeled truck, guiding means pivotally mounted thereon and movable angularly relative thereto, a motor reciprocable on said guiding means, motor reciprocating means driven by said motor, cutting mechanism operatively connected to said motor and including a forwardly extending cutter bar, and means driven by said motor for adjusting said bar into either a horizontal or a vertical position while said motor remains stationary.

24. In a mining machine, a wheeled truck, guiding means pivotally mounted thereon and movable angularly relative thereto, a motor reciprocable on said guiding means, 5 motor reciprocating means, cutting mechanism operatively connected to said motor and including a forwardly extending pivoted cutter bar, means driven by said motor for adjusting said bar into either a horizontal or a vertical position, and means driven by 10 said motor for swinging said bar about its pivot when in either position.
25. In a mining machine, a truck, guiding means thereon, a motor reciprocable relative 15 to said guiding means, cutting mechanism operatively connected to said motor and reciprocable therewith including a plane cutter bar disposable in a verticle plane and at an angle relative to said motor, and a jack operatively associated with said guiding means 20 and adapted to brace the latter.
26. In a mining machine, a truck, elongated guiding means thereon, a motor reciprocable relative to said guiding means, cutting mechanism operatively connected to said motor and reciprocable therewith including a plane cutter bar disposable in a vertical plane at an angle relative to said motor, and a jack operatively associated with said guiding means and located adjacent the front end 25 thereof.
27. In a mining machine, a truck, guiding means pivotally mounted thereon for movement about a vertical axis and projecting forwardly therefrom, cutting mechanism reciprocable in a substantially horizontal plane relative to said guiding means between positions in which it respectively overlies and is disposed wholly in advance of said truck, said cutting mechanism including a motor and a horizontally pivoted vertically disposed 30 plane cutter bar driven thereby, means for maintaining said guiding means stationary in a given angular position, means driven by said motor whereby the same may be reciprocated, and means for swinging said bar about its pivot operated by said motor.
28. In a mining machine, a truck, elongated guiding means thereon, a motor reciprocable relative to said guiding means, cutting mechanism operatively connected to 35 said motor and reciprocable therewith including a cutter bar disposable in a vertical plane at an angle to the horizontal and relative to said motor, and a jack pivotally mounted on said guiding means adjacent the front end thereof.
29. In a mining machine, a truck, guiding means for which said truck constitutes the sole support during transport carried on said truck and normally extending longitudinally 40 a substantial distance beyond the front end of the same, a motor reciprocable relative to said guiding means, cutting mechanism operatively connected to said motor and includ-
- ing a pivoted cutter bar, operative connections between said motor and said guiding means whereby the former is reciprocated relative to the latter to position said motor wholly beyond the front end of the truck, 70 and means for swinging said bar about its pivot when said motor is so disposed.
30. In a mining machine, a truck, guiding means swiveled thereon for horizontal swinging movement relative thereto and normally 75 extending longitudinally a substantial distance beyond the front end of the same, said truck providing the entire support for said guiding means during transport, a motor reciprocable relative to said guiding means, cutting mechanism operatively connected to said motor and including a pivoted cutter bar, operative connections between said motor and said guiding means whereby the former is reciprocated relative to the latter to position 80 said motor wholly beyond the front end of the truck, and means for swinging said bar about its pivot when said motor is so disposed.
31. In a mining machine, a truck, longitudinally disposed guiding means thereon, cutting mechanism movable longitudinally of said guiding means and including a pivoted cutter bar, and means whereby said cutter bar may be swung on its pivot beneath said guiding means and when between the ends of the latter. 90
32. In a mining machine, a truck, longitudinally disposed guiding means thereon extending forwardly therefrom for a substantial distance, cutting mechanism movable longitudinally of said guiding means and including a pivoted cutter bar, and means whereby said cutter bar may be swung on its pivot above or below said guiding means and when between the ends of the latter. 105
33. In a mining machine, a truck, longitudinally disposed guiding means thereon extending forwardly for a substantial distance, cutting mechanism movable longitudinally of said guiding means and including a pivoted cutter bar, and means whereby said cutter bar may be swung into a plane disposed beneath said guiding means or in a plane at right angles to said plane and when between the 110 ends of the latter.
34. In a mining machine, a truck, pivoted longitudinally disposed guiding means thereon extending forwardly therefrom for a substantial distance, cutting mechanism movable longitudinally of said guiding means and including a pivoted cutter bar, and means whereby said cutter bar may be swung on its pivot beneath said guiding means and when between the ends of the latter. 115
35. In a mining machine, a truck, longitudinally disposed guiding means thereon, bracing means adjacent the forward end thereof, cutting mechanism movable longitudinally of said guiding means and includ-

ing a pivoted cutter bar, and means whereby said cutter bar may be swung on its pivot beneath said guiding means and when between the ends of the latter.

5 36. In a mining machine, a truck, longitudinally disposed guiding means thereon extending forwardly therefrom for a substantial distance, cutting mechanism movable longitudinally of said guiding means 10 and including a pivoted cutter bar, and motor operated means whereby said cutter bar may be swung on its pivot beneath said guiding means and when between the ends of the latter.

15 37. In a mining apparatus, a truck, guiding means thereon, cutting apparatus movable relative to said guiding means during cutting comprising a pivoted cutter bar lying above the bottom of said guiding means, and 20 means for disposing said bar in a plane beneath said guiding means in positions wherein its pivot is respectively in front and rearward of the forward end of said guiding means.

25 38. In a mining apparatus, a truck, guiding means thereon, cutting apparatus movable relative to said guiding means during cutting comprising a pivoted cutter bar lying below the bottom of said guiding means, and 30 means for disposing said bar in a plane above said guiding means in positions wherein its pivot is respectively in front and rearward of the forward end of said guiding means.

35 39. In a mining apparatus, a truck, guiding means thereon, cutting apparatus movable relative to said guiding means during cutting comprising a pivoted cutter bar, and means for selectively disposing said bar in a plane below said guiding means or in an intersecting vertical plane, the bar pivot in 40 either position of said bar being disposable rearward of the forward end of said guiding means or in advance thereof.

45 40. In a mining apparatus, a truck, guiding means thereon, cutting mechanism movable rectilinearly relative to said guiding means comprising a pivoted cutter bar and a driving motor therefor, and means for adjusting said bar by power from said motor bodily angularly about an axis extending longitudinally of said guiding means selectively into different ones of a plurality of intersecting planes.

55 41. In a mining apparatus, a truck, guiding means thereon extending beyond the front end thereof, cutting mechanism movable over said guiding means to the front end thereof and comprising a cutter bar, and means for disposing said bar in a plane below said guiding means.

60 42. In a mining apparatus, a truck, guiding means thereon extending beyond the front end thereof, cutting mechanism movable relative to said guiding means to a position beyond the front end of said truck and com-

prising a frame and a cutter bar pivotally connected to said frame, means for disposing said bar in a plane below said guiding means, and means for swinging said bar in said plane.

65 43. In a mining apparatus, a truck, parallel guiding means thereon extending substantially beyond the front end thereof, said truck providing during transport the entire support for said guiding means, cutting mechanism movable relative to said guiding means and comprising a frame and a cutter bar pivoted thereto, a motor on said frame, means for disposing said frame and motor on the front end of said guiding means in a position wholly beyond the front end of said truck, and means for swinging said bar about its pivot when said frame is so disposed. 70 75 80

85 44. In a mining apparatus, a truck, parallel guiding means thereon extending substantially beyond the front end thereof, said truck providing during transport the entire support for said guiding means, cutting mechanism movable relative to said guiding means and comprising a frame and a cutter bar pivoted thereto, a motor on said frame, means for disposing said frame and motor on the front end of said guiding means in a position wholly beyond the front end of said truck, and means for swinging said bar about its pivot when said frame is so disposed. 90 95 100

105 45. In a mining apparatus, a truck, vertically disposed longitudinally extending guiding means thereon, cutting mechanism movable relative to said guiding means comprising a cutter bar, and means for disposing said bar in a plane below said guiding means in a position wherein the projections of said bar and guiding means on a horizontal plane will intersect. 110

115 46. In a mining apparatus, a truck, vertically disposed substantially horizontally extending guiding means thereon, cutting mechanism including a motor movable relative to said guiding means comprising a cutter bar, and means operable by said motor for selectively disposing said bar in a plane below said guiding means or in an intersecting plane. 120

125 47. In a mining apparatus, a truck, guiding means thereon, cutting mechanism including a motor movable relative to said guiding means longitudinally of the latter including a cutter bar, means operable by said motor for disposing said bar in a plane below said guiding means, and means for varying the position of said bar when so disposed relative to said truck. 130

135 48. In a mining apparatus, a truck, guiding means thereon, cutting mechanism movable relative to said guiding means longitudinally of the latter including a motor driving a cutter bar, means for disposing said bar in

a plane below said guiding means, and means operable by said motor for varying the angle of the plane in which said bar lies when so disposed relative to said truck.

49. In a mining apparatus, a truck, guiding means thereon, cutting mechanism movable relative to said guiding means including a motor driving a cutter bar, motor operated means for disposing said bar in a plane below said guiding means at will, and motor operated means for elevating the front end of said bar relative to the horizontal.

50. In a mining apparatus, a wheeled truck, a platform pivoted thereon on a horizontal pivot, cutting mechanism on said platform including a motor and an operatively connected cutter bar, said cutting mechanism being rotatable as a whole about an axis perpendicular to said platform and said cutter bar being swingable about a spaced parallel axis, truck driving mechanism including a motor, and means operatively connected to the second of said motors for tilting said platform about its pivot.

51. In a mining apparatus, a wheeled truck, a platform pivoted thereon upon a horizontal pivot, cutting mechanism on said platform including a swingable cutter bar having an axis of pivotal movement whose projection in the plane of the platform falls outside the boundaries of the latter, truck propelling mechanism, mechanism for tilting said platform about its pivot, and power means for effecting operation of said several mechanisms.

52. In a mining apparatus, a wheeled truck, a platform pivoted thereon, cutting mechanism on said platform including a frame and a cutter bar, said bar having a pivotal mounting providing for swinging movement of the bar about an axis whose projection on the plane of the platform falls outside the boundaries of the latter, truck driving mechanism including a motor, and means operatively connected to said motor for tilting said platform about its pivot.

53. In a mining apparatus, a frame, a motor carried thereby, means for feeding said frame relative to a working face driven by said motor, and cutting mechanism including a cutter bar pivoted to swing about an axis perpendicular to its plane of cut, means for supporting said cutter bar for swinging movement in intersecting planes including a support for said bar on which the latter is pivotally mounted, said support being pivotally mounted for rotation about an axis perpendicular to the axis of swing of said bar, and mechanism driven by said motor for swinging said bar about its pivot and for moving said support about said second mentioned axis to change the plane of cut of said bar.

54. In a mining apparatus, a motor, means for feeding said motor relative to a working face including feeding means driven by said

motor, and cutting means including a support rotatable about a horizontal axis, a cutter bar pivotally mounted on said support for swinging movement about an axis perpendicular to the axis of rotation of said support, but spaced longitudinally of said second mentioned axis from said first mentioned axis, and means driven by said motor for effecting movement of support about its axis or swing of said bar about its axis.

55. In a mining apparatus, a frame, a motor supported thereon and having a power shaft rotatable on a horizontal axis arranged longitudinally of said frame, frame moving means including elements adjacent either side of said frame and rotatable on axes parallel to a single line and operative on rotation to effect translation of said frame and driving means operative to effect rotation of either of said elements in either direction including operative connections including a plurality of clutches between said elements and said motor, and cutting mechanism carried by said frame and driven by said motor including a pivoted cutter bar operative to cut in a vertical plane.

56. In a mining apparatus, a frame, a motor supported thereon and having a power shaft rotatable on a horizontal axis arranged longitudinally of said frame, frame moving means including elements adjacent either side of said frame and rotatable on axes parallel to a single line and operative on rotation to effect translation of said frame and driving means operative to effect rotation of either of said elements in either direction including operative connections including a plurality of clutches between said elements and said motor, and cutting mechanism carried by said frame and driven by said motor including a pivoted plane cutter bar adjustable into and operative to cut in a horizontal or in a vertical plane.

57. In a mining machine, a truck longitudinally disposed guiding means swiveled thereon, cutting means movable longitudinally of said guiding means and including a motor and a pivoted cutter bar, and means whereby the pivot of said cutter bar may be bodily rotated by power from said motor to position said pivot in parallelism with different sides of an angle.

58. In a mining machine, a truck, longitudinally disposed guiding means swiveled thereon, cutting means movable longitudinally of said guiding means and including a motor and a pivoted cutter bar, and means whereby the pivot of said cutter bar may be bodily rotated to position said pivot in parallelism with different sides of an angle or bodily translated rectilinearly by power from said motor.

59. In a mining machine, a frame, a bracket carried thereby, a swinging cutter bar, means for pivotally supporting said cutter

bar for swinging movement relative to said bracket about an axis perpendicular to the plane of cut of said bar, and cooperating means carried by said bracket and said bar for transmitting a bar swinging force to the latter at a point between its pivot and the extremity of its cutting portion, said means carried by said bar comprising an arcuate rack and said means carried by said bracket including a rotatable element meshing with said rack and disposed between the outer end of the bar and the pivot of the latter when the bar is in its median position.

60. In a mining machine, a support, cutting mechanism thereon including a swiveled cutter bar carrying a cutter chain, said bar being adjustable bodily into positions to cut in different ones of a plurality of intersecting planes all of which are parallel to a single line, a motor for operating said cutter chain, means operable by said motor to effect said bodily movement of said bar to the desired plane and to swing said bar in any plane to which it may be moved, and means for effecting bodily rectilinear movement of said bar in the direction of said line in the different planes of adjustment thereof.

61. In a mining machine, a support, cutting mechanism thereon including a swiveled cutter bar carrying a cutter chain, said bar being adjustable bodily into positions to cut in different ones of a plurality of intersecting planes all of which are parallel to a single line, a motor for operating said cutter chain, means operable by said motor to effect said bodily movement of said bar to the desired plane and to swing said bar in any plane to which it may be moved, and means to effect bodily rectilinear movement of said bar in the direction of said line at a plurality of speeds in the planes to which the same may be adjusted.

62. In a mining machine, a support, cutting mechanism thereon including a swiveled cutter bar carrying a cutter chain, said bar being adjustable bodily into positions to cut in different ones of a plurality of intersecting planes all of which are parallel to a single line, a motor for operating said cutter chain, means operable by said motor to effect said bodily movement of said bar to the desired plane and to swing said bar in any plane to which it may be moved, and means operable by said motor to effect bodily rectilinear movement parallel to said line in opposite directions of said bar while said cutter chain is operated in the same direction by said motor.

63. In a mining machine, a support, cutting mechanism thereon including a swiveled cutter bar carrying a cutter chain, said bar being adjustable bodily into positions to cut in different ones of a plurality of intersecting planes all of which are parallel to a single line, a motor for operating said cutter

chain, and means operable by said motor to effect said bodily movement of said bar to the desired plane, to move said bar bodily rectilinearly in such plane, to swing the same therein, and to retract the same to effect the formation in such plane of a parallel ribbed kerf of greater width than the width of said bar and whose ribs are parallel to said single line.

64. In a mining machine, a support, cutting mechanism thereon including a swiveled cutter bar carrying a cutter chain, said bar being adjustable bodily into positions to cut in different ones of a plurality of intersecting planes all of which are parallel to a single line, a motor for operating said cutter chain, and means operable by said motor to effect said bodily movement of said bar to the desired plane, to move said bar bodily rectilinearly in such plane, to swing the same therein, and to retract the same to effect the formation in such plane of a parallel ribbed kerf of greater width than the length of said bar and whose ribs are parallel to said single line.

65. In a mining apparatus, supporting means movable on a trackway, cutter mechanism thereon comprising a pivotally mounted cutter bar having a chain adapted to cut a kerf for said bar in a face when said bar is presented edgewise thereto, self-contained power operated means for moving said bar bodily rectilinearly of the trackway, about its pivot in the same plane, and reversely rectilinearly of the trackway to insert a parallel ribbed kerf in a face in front of the end of the trackway, and self-contained means operated by said motor to move said bar bodily about an axis extending longitudinally of the trackway selectively into different intersecting planes in each of which said movements may be effected.

66. In a mining apparatus, supporting means movable on a trackway, cutter mechanism thereon comprising a pivotally mounted cutter bar having a chain adapted to cut a kerf for said bar in a face when said bar is presented edgewise thereto, self-contained power operated means for moving said bar bodily rectilinearly in a path extending longitudinally of the trackway but making an angle therewith, about its pivot in the same plane, and reversely rectilinearly in its path of rectilinear movement to insert a parallel ribbed kerf in a face in front of the end of the trackway, and self-contained means operated by said motor to move said bar bodily about an axis extending longitudinally of the trackway selectively into different intersecting planes in each of which said movements may be effected.

67. In a mining apparatus, a wheeled truck mounted on a trackway, cutter mechanism thereon comprising a motor and a pivotally mounted cutter chain carrying

- 5 cutter bar, a self-contained power operated mechanism supported by said truck for moving said bar either angularly across the end of said truck or longitudinally relative to the trackway at a feeding speed to cut either a right angle or a parallel face, and self-contained motor operated means for bodily adjusting said bar about an axis extending longitudinally of the trackway and intermediate the sides thereof.
- 10 68. In a mining apparatus, a wheeled truck movable on a trackway, cutter mechanism thereon comprising a motor and a pivotally mounted cutter chain-carrying cutter bar adapted to swing across the end of the truck, self-contained power operated mechanism supported solely by said truck for moving said bar angularly relative to said trackway and reversely longitudinally relative thereto during cutting, and self-contained motor operated means for bodily adjusting said bar about an axis extending longitudinally of the trackway and intermediate the sides thereof.
- 15 69. In a mining apparatus, a wheeled truck movable on a trackway, cutter mechanism including a cutter bar disposable in fixed relation at acute angles to the trackway and pivotally mounted on said truck, self-contained power operated means supported on said truck for moving the bar when so disposed rectilinearly in a path extending longitudinally of the trackway but making an angle with the plane of the latter, relatively transversely in the same plane, and reversely rectilinearly to form a parallel ribbed kerf of a depth substantially equal to the length of the bar and in the face in front of the end of the trackway, and means, self-contained and power operated, for changing the plane of the kerf and operative to move said bar bodily about an axis extending longitudinally of the trackway and disposed in a vertical plane extending between the sides of the trackway.
- 20 70. In a mining machine, a support, cutting mechanism thereon including a swiveled cutter bar carrying a cutter chain, said bar being adjustable bodily into cutting position in different ones of a plurality of intersecting planes; a motor for operating said cutter chain and having driving pinions at opposite ends thereof, means operable by said motor to effect said bodily movement of said bar to the desired plane and to swing said bar in any plane into which it may be moved, and to effect bodily rectilinear movement of said bar in the planes thereof, said bodily rectilinear movement effecting means and said bar swinging means being actuated by pinions at opposite ends of said motor.
- 25 71. In a mining machine, a support, cutting mechanism thereon including a swiveled cutter bar carrying a cutter chain, said bar being adjustable bodily into cutting position being adjustable bodily into cutting position
- 30 in different ones of a plurality of intersecting planes, a motor for operating said cutter chain and having driving pinions at opposite ends thereof, means operable by said motor to effect said bodily movement of said bar to the desired plane and to swing said bar in any plane into which it may be moved, and to effect bodily rectilinear movement of said bar in the planes thereof, said bodily rectilinear movement effecting means and said bar swinging means being actuated by pinions at opposite ends of said motor, and said pinions rotating on an axis extending longitudinally of said support and said bar swinging means being actuated by said pinion which is nearer to said bar.
- 35 72. In a mining machine, a wheeled support, longitudinally extending vertically disposed guiding means thereon, a motor reciprocable in said guiding means between the top and bottom thereof and between the ends of said guiding means, motor reciprocating means, and cutting mechanism operatively connected to said motor including a forwardly extending horizontally disposed pivoted cutter bar.
- 40 73. In a mining machine, a wheeled support, longitudinally extending guiding means arranged thereon in a vertical plane, a motor reciprocable relative to said guiding means between the top and bottom thereof and between the ends thereof, motor reciprocating means, and cutting mechanism operatively connected to said motor including a forwardly extending vertically disposed pivoted cutter bar and means operable by power from said motor for swinging said bar about its pivot.
- 45 74. In a mining machine, a support, longitudinally disposed guiding means thereon, a motor reciprocable relative to said guiding means and between the ends thereof, cutting mechanism operatively connected to said motor and including a longitudinally extending pivoted cutter bar, means for rotating said bar bodily about a longitudinally disposed axis, means for swinging said bar about its pivot, and means for reciprocating said motor relative to said guiding means including mechanical driving connections between said motor and said guiding means.
- 50 75. In a mining machine, a wheeled support, longitudinally extending guiding means thereon, a motor reciprocable between the ends of said guiding means, motor reciprocating means including a rotatable element movable bodily with said motor and a co-operating element fixed relative to said guiding means and with which said rotatable element cooperates to effect motor movement, and cutting mechanism operatively connected to said motor including a forwardly extending vertically disposed horizontally pivoted plane cutter bar.
- 55 76. In a mining machine, a wheeled sup-

port, longitudinally extending guiding means thereon, a motor reciproccable between the ends of said guiding means, motor reciproccating means including a rotatable element movable bodily with said motor and a cooperating element fixed relative to said guiding means and with which said rotatable element cooperates to effect motor movement, and cutting mechanism operatively connected to said motor including a forwardly extending vertically disposed horizontally pivoted plane cutter bar and means for swinging said bar by power from said motor.

77. In a mining machine, a wheeled support, longitudinally extending guiding means thereon, a motor reciproccable between the ends of said guiding means, motor reciproccating means including a rotatable element movable bodily with said motor and a cooperating element fixed relative to said guiding means and with which said rotatable element cooperates to effect motor movement, and cutting mechanism operatively connected to said motor including a forwardly extending vertically disposed horizontally pivoted plane cutter bar and means for changing the plane of said bar.

78. In a mining machine, a wheeled support, longitudinally extending guiding means thereon, a motor reciproccable between the ends of said guiding means, motor reciproccating means including a rotatable element movable bodily with said motor and a cooperating element fixed relative to said guiding means and with which said rotatable element cooperates to effect motor movement, and cutting mechanism operatively connected to said motor including a forwardly extending vertically disposed horizontally pivoted plane cutter bar and means for changing the plane of said bar to a horizontal plane.

79. In a mining machine, a wheeled support, longitudinally extending guiding means thereon, a motor reciproccable between the ends of said guiding means, motor reciproccating means including a rotatable element movable bodily with said motor and a cooperating element fixed relative to said guiding means and with which said rotatable element cooperates to effect motor movement, and cutting mechanism operatively connected to said motor including a forwardly extending vertically disposed horizontally pivoted plane cutter bar and means for swinging said bar by power from said motor and for changing the plane of said bar.

80. In a mining machine, a wheeled support, longitudinally extending guiding means thereon, a motor reciproccable between the ends of said guiding means, motor reciproccating means including a rotatable element movable bodily with said motor and a cooperating element fixed relative to said guiding means and with which said rotatable

element cooperates to effect motor movement, and cutting mechanism operatively connected to said motor including a forwardly extending vertically disposed horizontally pivoted plane cutter bar and means for swinging said bar by power from said motor and for changing the plane of said bar to a horizontal plane.

81. In a mining machine, a frame, supporting means carried thereby, a swinging cutter bar, means for pivotally supporting said cutter bar for swinging movement relative to said supporting means about an axis perpendicular to the plane of cut of said bar, and means for transmitting a bar swinging force to said bar at a point between its pivot and the extremity of its cutting portion including a rack fixed with respect to said bar, a pinion carried on said supporting means meshing with said rack and rotating on a stationary axis during bar swing, a worm wheel coaxial with said pinion, a worm meshing with said worm wheel, a second worm wheel coaxial with said worm, and a worm rotatable on an axis parallel to the axis of rotation of said pinion for driving said second worm wheel.

82. In a mining machine, a frame, supporting means carried thereby, a swinging cutter bar, means for pivotally supporting said cutter bar for swinging movement relative to said supporting means about an axis perpendicular to the plane of cut of said bar, and means for transmitting a bar swinging force to said bar at a point between its pivot and the extremity of its cutting portion including a rack fixed with respect to said bar, a pinion carried on said supporting means meshing with said rack and rotating on a stationary axis during bar swing, and means for effecting rotation of said pinion including a worm rotating on an axis parallel to the axis of said pinion, and power transmission connections between the same.

83. In a mining machine, a frame, supporting means carried thereby, a swinging cutter bar, means for pivotally supporting said cutter bar for swinging movement relative to said supporting means about an axis perpendicular to the plane of cut of said bar, and means for transmitting a bar swinging force to said bar at a point between its pivot and the extremity of its cutting portion including a rack fixed with respect to said bar, a pinion carried on said supporting means meshing with said rack and rotating on a stationary axis during bar swing, and means for effecting rotation of said pinion including a worm rotating on an axis parallel to the axis of said pinion and nearer said frame than said pinion, and power transmission connections between the same.

84. In a mining machine, a frame, supporting means carried thereby, a swinging cutter bar, means for pivotally supporting said

5 cutter bar for swinging movement relative to said supporting means about an axis perpendicular to the plane of cut of said bar, and means for transmitting a bar swinging force to said bar at a point between its pivot and the extremity of its cutting portion including a toothed member fixed relative to said bar and having teeth arranged in a series 10 equi-distantly spaced from the axis of bar swing, and an actuating member meshing with said teeth and rotatable on a stationary axis, and actuating means for said actuating member including a worm rotating on an axis parallel to a line parallel to the axis of bar swing, and power transmission connections 15 between the same and said actuating member.

85. In a mining machine, a frame, supporting means carried thereby, a swinging cutter bar, means for pivotally supporting said cutter bar for swinging movement relative to said supporting means about an axis perpendicular to the plane of cut of said bar, and means for transmitting a bar swinging force to said bar at a point between its pivot and the extremity of its cutting portion including a toothed member fixed relative to said bar and having teeth arranged in a series equi-distantly spaced from the axis of bar swing, and 20 an actuating member meshing with said teeth and rotatable on a stationary axis, and actuating means for said actuating member including a worm rotating on an axis parallel to a line parallel to the axis of bar swing and nearer said frame than said actuating member, and power transmission connections between the same and said actuating member.

86. In a mining apparatus, a frame supporting pivotally mounted cutting mechanism, said cutting mechanism comprising a plane cutter bar and means for supporting the same in planes bearing different space relations to said frame, supporting means for said frame including wheeled axles spaced 45 longitudinally of said frame beneath the latter and adapted to run upon a trackway, and means for tilting said frame about a horizontal axis for effecting a change in plane of said frame relative to the trackway upon which 50 said wheels are supported including a threaded member rotatable on a horizontal axis and power means for rotating the same.

87. In a mining apparatus, a wheel supported frame, cutting mechanism supported thereon and adjustable relative thereto to vary the plane of cut thereof, and means for varying the plane of cut of said cutting mechanism including a vertically disposed screw, a nut supported on said wheel supported frame 60 and fixed against bodily movement relative thereto, and power means for effecting rotation of said nut.

88. In a mining apparatus, a wheel supported frame, cutting mechanism supported 65 thereon and adjustable relative thereto to

vary the plane of cut thereof, and means for varying the plane of cut of said cutting mechanism including a vertically disposed screw, a nut supported on said wheel supported frame and fixed against bodily movement 70 relative thereto, and power means for effecting rotation of said nut including a motor on said wheel supported frame.

89. In a mining apparatus, a frame, cutting mechanism mounted thereon for swinging movement in the planes thereof and for adjustment about an axis extending longitudinally of said frame midway between the sides thereof and into different intersecting planes parallel to said axis, and propulsion mechanism for said frame including a pinion rotating on an axis transverse to the longitudinal dimension of said frame, a worm rotating on an axis extending longitudinally of said frame, operative connections between 85 said worm and pinion, said worm and pinion moving, on longitudinal movement of said frame, bodily with said frame, and power means for effecting rotation of said worm to effect longitudinal movement of said frame. 90

90. In a mining machine, kerf cutting mechanism including an elongated plane cutter bar carrying an orbitally movable cutter chain, a support for said kerf cutting mechanism, a frame on which said support is pivotally mounted for swinging movement in a substantially horizontal plane, a second frame member having pivotal connection with the first frame member upon a longitudinally extending axis whereby the cutting 95 mechanism and support may be tilted on a longitudinal axis, a motor on said second frame member, operative connections between said motor and said kerf cutting mechanism, and mechanism actuated by said motor for 100 effecting swinging movement of said cutting mechanism support to effect bar swing, and a wheeled truck having pivotal connection with the second frame member upon a transverse axis whereby the second frame member may 110 rock on a transverse axis.

91. In a mining machine, a wheeled support, a frame member having pivotal bearing on said support to rock on a transverse axis, a second frame member having pivotal bearing on the first frame member to rock on a longitudinal axis, kerf cutting mechanism including an elongated plane cutter bar carrying an orbitally movable cutter chain, said cutter bar being mounted on said second frame and having angular movement with respect thereto, a motor mounted on the first frame member, a shaft operatively connected with said motor and concentric with the pivotal bearing of said second frame member, said shaft being operatively connected with the cutter chain whereby the latter may be driven in several positions, and means wholly mounted on said wheeled support and actuated 120 125 130

by said motor for swinging said cutter bar by power relative to said second frame.

92. In a mining machine, a wheeled support, a frame member pivotally connected with the support to rock on a transverse axis, a second frame member pivotally connected to the first frame member to rock on a longitudinal axis, cutting mechanism including a plane cutter bar mounted on said second frame and swingable with respect thereto to cut a plane kerf, a motor actuating said cutting mechanism, and means operated by said motor for raising and lowering said cutting mechanism to change the plane of the kerf cut thereby.

93. In a mining machine, a wheeled support, a frame member pivotally connected with said support to rock on a transverse axis, a cutting mechanism mounted at the forward end of said frame member including an elongated plane cutter bar carrying an orbitally movable cutter chain, said cutter bar mounted for angular movement with respect to said frame member whereby a swinging cut may be made, and motor devices mounted at the rear end of the machine having driving connection with said cutting mechanism and said wheeled support.

94. In a mining machine, a wheeled support, a frame member pivotally connected with said support to rock on a transverse axis, a cutting mechanism mounted at the forward end of said frame member including an elongated plane cutter bar carrying an orbitally movable cutter chain, said cutter bar mounted for angular movement with respect to said frame member whereby a swinging cut may be made, motor devices mounted at the rear end of the machine having driving connection with said cutting mechanism and said wheeled support, and motor operated mechanism wholly supported on said wheeled support for effecting bar swing at a cutting speed.

95. In a mining machine, a wheeled truck, kerf cutting mechanism thereon including a pivoted cutter bar rotatable about a longitudinal axis and movable longitudinally relative to said truck, a motor movable longitudinally with said bar, and means operated by said motor for moving said bar longitudinally of said truck or laterally in a plane about its pivot.

96. In a mining machine, a wheeled truck, a frame comprising a guideway, mechanism movable longitudinally along said guideway including a motor and vertical kerf cutting mechanism of the cutter chain type disposed with its orbit in a vertical plane, mechanism propelled by said motor for feeding the same and said cutting mechanism along said guideway, a pivotal connection between said guideway and the truck permitting pivoting of said guideway about a horizontal axis, and motor driven means for tilting said guideway about said axis.

97. In a mining machine, a wheeled truck, a frame comprising parallel guiding elements disposed one above the other in a substantially vertical plane on said truck, mechanism movable longitudinally along said guiding elements including a motor and cutting mechanism of the cutter chain type disposed with its orbit parallel to the substantially vertical plane of said guiding elements, mechanism propelled by said motor for feeding the same and said cutting mechanism along said guiding elements, a pivotal connection between said guiding frame and the truck permitting tilting of said guiding elements about a horizontal axis, and motor driven means for tilting said guiding frame about said axis.

98. In a mining machine, a wheeled truck, a frame comprising parallel top and bottom guideways disposed one above the other in a substantially vertical plane on said truck, mechanism movable longitudinally along said guideways including a motor and vertical kerf cutting mechanism including a cutting element of the cutter chain type disposed with its orbit parallel to the plane of said guideways and adapted to swing in a vertical plane, mechanism propelled by said motor for feeding the same and said cutting mechanism along said guideways, a pivotal connection between said guiding frame and the truck permitting tilting of said guideways about a horizontal axis, and motor driven means for tilting said guiding frame about said axis.

99. In a mining machine, a wheeled truck, a frame comprising parallel top and bottom guideways disposed one above the other in a substantially vertical plane on said truck, mechanism movable longitudinally along said guideways including a motor and vertical kerf cutting mechanism including a cutting element of the cutter chain type disposed with its orbit parallel to the substantially vertical plane of said guideways, mechanism including a rack carried by one of said guideways and a pinion carried by said mechanism and propelled by said motor for feeding the same and said cutting mechanism along said guideways, a pivotal connection between said guiding frame and the truck permitting tilting of said guideways about a horizontal axis, and motor driven means for tilting said guiding frame about said axis.

100. In a mining machine, a wheeled truck, power operated truck propulsion mechanism, a guideway carried by said truck, and cutting mechanism reciprocable in said guideway including a cutter bar swingable in a vertical plane, power operated gearing for effecting swinging of said bar, a cutter chain on said bar, power operated means for effecting circulation of said cutter chain, and power operated means for effecting reciprocation of said cutting mechanism, all of said power operated means being self-contained.

101. In a mining machine, a cutter chain

carrying cutter bar swingable in a substantially vertical plane to make a shearing cut, a motor provided with a plurality of power transmitting elements, a portable guideway 5 upon which said motor is reciprocable, chain actuating mechanism, bar swinging mechanism, and motor feeding mechanism, one of said mechanisms being driven by one of said power transmitting elements and another by another.

10 102. In a mining machine, a cutter chain carrying cutter bar swingable in a substantially vertical plane to make a shearing cut, a motor provided with a plurality of power transmitting elements, a portable guideway upon which said motor is reciprocable, chain actuating mechanism, bar swinging mechanism, and motor feeding mechanism, two of said mechanisms being driven by one of said 15 power transmitting elements and the third by the other.

103. In a mining machine, a cutter chain carrying cutter bar swingable in a substantially vertical plane to make a shearing cut, 25 a motor provided with a plurality of power transmitting elements, a portable guideway upon which said motor is reciprocable, chain actuating mechanism, bar swinging mechanism, motor feeding mechanism, and mechanism for changing the plane of cut of said bar, 30 certain of said mechanisms being driven by one of said power transmitting elements and the remainder by another.

104. In a mining machine, the combination comprising a wheeled truck frame, a guiding frame swiveled thereon and having longitudinally extending guideways, a machine body mounted for sliding movement in said guideways, cutting mechanism carried by said body including a cutter bar swingable in a vertical plane, and motor driven mechanism for swinging said cutter bar and for driving the wheels of said truck.

105. In a mining machine, the combination
45 of a wheeled truck frame, a guiding frame
swiveled thereon for movement in a horizontal
plane and having longitudinally extending
guideways, a machine body slidably
mounted in said guideways, cutting mecha-
nism carried by said body including a cutter
50 bar swingable in a vertical plane, and motor
driven mechanism for swinging said cutter
bar and for driving the wheels of said truck.

53 106. In a mining machine, the combination comprising a wheeled truck frame, a guiding frame swiveled thereon and having longitudinally extending guideways, a machine body mounted for sliding movement in said guideways, cutting mechanism carried by said body including a cutter bar swingable in a vertical plane, and motor driven mechanism for swinging said cutter bar, for driving the wheels of said truck, and for moving said machine within said guideways.

65 107. In a mining machine, the combination

of a wheeled truck frame, a guiding frame swiveled thereon for movement in a horizontal plane and having longitudinally extending guideways, a machine body slidably mounted in said guideways, cutting mechanism carried by said body including a cutter bar swingable in a vertical plane, and motor driven mechanism for swinging said cutter bar, for driving the wheels of said truck, and for moving said machine within said guideways.

ways. 108. In a mining machine, the combination of a wheeled truck frame, a guiding frame swiveled thereon and having longitudinally extending guideways, a machine body slidably mounted in said guideways, a motor carried within said body, cutting mechanism carried by said body including a cutter bar swingable in a vertical plane, and mechanism driven by said motor for actuating said cutting mechanism. 85

109. In a mining machine, the combination of a wheeled truck frame, a guiding frame swiveled thereon and having longitudinally extending guideways, a machine body slidably mounted in said guideways, a motor carried within said body, cutting mechanism carried by said body including a cutter bar swingable in a vertical plane, and mechanism driven by said motor for actuating said cutting mechanism and for swinging said cutter bar about its pivot.

110. In a mining machine, the combination of a wheeled truck frame, a guiding frame swiveled thereon and having longitudinally extending guideways, a machine body slidably mounted in said guideways, a motor carried within said body, cutting mechanism carried by said body including a cutter bar swingable in a vertical plane, and mechanism driven by said motor for actuating said cutting mechanism, for swinging said cutter bar about its pivot, and for moving said machine body in said guideways. 100 105

111. In a mining machine, the combination of a wheeled truck frame, and a guiding frame swiveled thereon for movement in a horizontal plane and having longitudinally extending guideways, a machine body slidably mounted in said guideways, cutting mechanism carried by said body including a cutter bar swingable in a vertical or a horizontal plane, and motor actuated devices for driving the wheels of said truck, for swinging said cutter bar, and for moving said machine body in said guideways. 110 115 120

112. In a mining machine, the combination of a wheeled truck frame, a guiding frame swiveled thereon for movement in a horizontal plane and having longitudinally extending guideways, said guiding frame also being adjustable about a transverse horizontal axis, a machine body slidably mounted in said guideways, cutting mechanism carried by said body including a cutter bar swingable in a 130

vertical plane, and motor actuated devices for driving the wheels of said truck, for swinging said cutter bar, and for moving said body in said guideways.

113. In a mining machine, the combination of a wheeled truck, a guiding frame swiveled thereon for movement in a horizontal plane and having longitudinally extending guideways, said guiding frame also being adjustable upon a transverse horizontal axis, a machine body slidably mounted in said guideways, cutting mechanism carried by said body including a swingable cutter bar, and motor actuated devices for driving said cutting mechanism, for swinging said bar, for driving the wheels of said truck, and for moving said body in said guideways.

114. In combination, a truck, a frame, a swivel between said truck and frame, kerf cutting mechanism on said frame including a pivoted laterally movable cutter bar, means for moving said bar longitudinally and laterally relative to said frame, and means including a horizontal pivot between said truck and frame for adjusting said kerf cutting mechanism in a vertical plane relative to said frame.

115. In a mining machine, the combination with a plurality of movable supports adjustable about laterally offset, substantially horizontal, parallel axes and jointly adjustable about one of the same, of a kerf cutter movably mounted on one of said supports, and power means for selectively adjusting either of said supports or moving said cutter to cut a plane kerf parallel to said axes while said supports remain stationary.

116. In a mining machine, the combination with a plane kerf cutter having cutting elements movable along its length adapted to cut a plane kerf to admit said cutter, of supporting means therefor adapted to permit angular adjustment thereof about a plurality of parallel horizontal axes, said cutter being adapted to cut kerfs in planes substantially parallel to said axes, and power operated means for moving said cutter bodily toward and from one of said axes.

117. In a mining apparatus, a support, a normally longitudinally disposed transversely disposable horizontal kerf cutter supporting and guiding frame of materially greater length than the width of said support mounted on and wholly supported by the latter for movement relative thereto about a vertical axis into positions respectively longitudinal and transverse with respect to said support, and kerf cutting mechanism including a swingable cutter bar and a motor relative to which said bar is swingable, said cutting mechanism being movable along said frame between the ends thereof to insert a kerf in advance of the side thereof.

118. In a mining apparatus, a support, a normally longitudinally disposed transversely disposable kerf cutter supporting and

guiding frame of materially greater length than the width of said support mounted on and wholly supported by the latter for movement relative thereto about a vertical axis into positions respectively longitudinal and transverse with respect to said support, and kerf cutting mechanism movable thereon including a swingable cutter bar and a motor relative to which said bar is swingable, said cutting mechanism being movable between the ends of said frame to insert a kerf at either the side or end of said frame.

119. Mining apparatus including a frame supporting at one end thereof cutting mechanism, and means for effecting propulsion of said apparatus during cutting in a path parallel to the major dimension of said frame including at the end of said frame remote from said cutting mechanism a driving member rotatable upon a horizontal axis extending longitudinally of said frame, and driving means for said cutting mechanism and said member including a common motor disposed between said cutting mechanism and said member on said frame, the driving mechanism for said member including reversing gearing.

120. Mining apparatus including a frame supporting at one end thereof cutting mechanism, and means for effecting propulsion of said apparatus during cutting in a path parallel to the major dimension of said frame including at the end of said frame remote from said cutting mechanism a driving member rotatable upon a horizontal axis extending longitudinally of said frame, and driving means for said cutting mechanism and said member including a common motor disposed between said cutting mechanism and said member on said frame and having a power shaft parallel to the axis of rotation of said member, the driving mechanism for said member including reversing gearing.

121. In a mining machine, kerf cutting mechanism including an elongated plane cutter bar carrying an orbitally movable cutter chain, a support for said kerf cutting mechanism, a frame member on which said support is pivotally mounted for swinging movement in a substantially horizontal plane, a second frame member having pivotal connection with the first frame member about a longitudinally extending axis whereby the cutting mechanism and support may be tilted on a longitudinal axis, a wheeled truck having pivotal connection with the second frame member upon a transverse axis whereby the second frame member may rock on a transverse axis, and motor operated devices for swinging the support for said kerf cutting mechanism relative to said first frame member to effect swinging movement of the cutter bar at a cutting speed.

122. In a mining machine, kerf cutting mechanism including an elongated plane cut-

- ter bar carrying an orbitally movable cutter chain, a support for said kerf cutting mechanism, a frame member on which said support is pivotally mounted for swinging movement in a substantially horizontal plane, a second frame member having pivotal connection with the first frame member about a longitudinally extending axis whereby the cutting mechanism and support may be tilted on a longitudinal axis, a wheeled truck having pivotal connection with the second frame member upon a transverse axis whereby the second frame member may rock on a transverse axis, and motor operated devices for effecting rocking movement of said second frame member about its axis at a bar positioning speed to change the plane of operation of said cutter bar.
123. In a mining machine, kerf cutting mechanism including an elongated plane cutter bar carrying an orbitally movable cutter chain, a support for said kerf cutting mechanism, a frame member on which said support is pivotally mounted for swinging movement in a substantially horizontal plane, a second frame member having pivotal connection with the first frame member about a longitudinally extending axis whereby the cutting mechanism and support may be tilted on a longitudinal axis, a wheeled truck having pivotal connection with the second frame member upon a transverse axis whereby the second frame member may rock on a transverse axis, motor operated devices for swinging the support for said kerf cutting mechanism relative to said first frame member to effect swinging movement of the cutter bar at a cutting speed, motor operated devices for effecting rocking movement of said second frame member about its axis at a bar positioning speed to change the angle of said cutter bar relative to the horizontal, and motor operated devices for effecting rectilinear movements of said cutter bar at a cutting speed to effect sumping and withdrawal cuts and for swinging said cutter bar at a cutting speed to effect a transverse cut.
124. In a mining machine, kerf cutting mechanism including an elongated plane cutter bar carrying an orbitally movable cutter chain, a support for said kerf cutting mechanism, a frame member on which said support is pivotally mounted for swinging movement in a substantially horizontal plane, a second frame member having pivotal connection with the first frame member about a longitudinally extending axis whereby the cutting mechanism and support may be tilted on a longitudinal axis, a wheeled truck having pivotal connection with the second frame member upon a transverse axis whereby the second frame member may rock on a transverse axis, motor operated devices for swinging the support for said kerf cutting mechanism relative to said first frame member to effect swinging movement of the cutter bar at a cutting speed, and motor operated devices for effecting rectilinear movements of said cutter bar at a cutting speed to effect sumping and withdrawal cuts and for swinging said cutter bar at a cutting speed to effect a transverse cut.
125. In a mining machine, kerf cutting mechanism including an elongated plane cutter bar carrying an orbitally movable cutter chain, a support for said kerf cutting mechanism, a frame member on which said support is pivotally mounted for swinging movement in a substantially horizontal plane, a second frame member having pivotal connection with the first frame member about a longitudinally extending axis whereby the cutting mechanism and support may be tilted on a longitudinal axis, a wheeled truck having pivotal connection with the second frame member upon a transverse axis whereby the second frame member may rock on a transverse axis, motor operated devices for swinging the support for said kerf cutting mechanism relative to said first frame member to effect swinging movement of the cutter bar at a cutting speed, and motor operated devices for effecting rectilinear movements of said cutter bar at a cutting speed to effect sumping and withdrawal cuts and for swinging said cutter bar at a cutting speed to effect a transverse cut.
126. In a mining machine, a wheeled support, a frame member having pivotal bearing on said support to rock on a transverse axis, a second frame member having pivotal bearing on the first frame member to rock on a longitudinal axis, kerf cutting mechanism including an elongated plane cutter bar carrying an orbitally movable cutter chain, said cutter bar being mounted on said second frame member and having angular movement with respect thereto, a motor mounted on said first frame member, mechanism driven by said motor for driving the cutter chain in any position of said bar including a shaft concentric with the pivotal bearing of said second frame member, said shaft being operatively connected with the cutter chain, and mechanism driven by said motor for effecting angular movement of said bar at a cutting speed relative to said second frame member.
127. In a mining machine, a wheeled support, a frame member having pivotal bearing on said support to rock on a transverse axis, a second frame member having pivotal bearing on the first frame member to rock on a longitudinal axis, kerf cutting mechanism including an elongated plane cutter bar carrying an orbitally movable cutter chain, said cutter chain being mounted on said second frame member and having angular movement with respect thereto, a motor mounted on said first frame member, mechanism driven by said motor for driving the cutter chain in any position of said bar including a shaft concentric with the pivotal bearing of said second frame member, said shaft being operatively connected with the cutter chain, and mechanism driven by said motor for effecting angular movement of said bar at a cutting speed relative to said second frame member.

chain in any position of said bar including a shaft concentric with the pivotal bearing of said second frame member, said shaft being operatively connected with the cutter chain, and mechanism driven by said motor for rocking said second frame member about its axis at a bar positioning speed to change the plane of operation of the cutter bar.

128. In a mining machine, a wheeled support, a frame member having pivotal bearing on said support to rock on a transverse axis, a second frame member having pivotal bearing on the first frame member to rock on a longitudinal axis, kerf cutting mechanism including an elongated plane cutter bar carrying an orbitally movable cutter chain, said cutter chain being mounted on said second frame member and having angular movement with respect thereto, a motor mounted on said first frame member, mechanism driven by said motor for driving the cutter chain in any position of said bar including a shaft concentric with the pivotal bearing of said second frame member, said shaft being operatively connected with the cutter chain, mechanism driven by said motor for effecting angular movement of said bar at a cutting speed relative to said second frame member, and mechanism driven by said motor for rocking said second frame member about its axis at a bar positioning speed to change the plane of operation of the cutter bar.

129. In a mining machine, a wheeled support, a frame member having pivotal bearing on said support to rock on a transverse axis, a second frame member having a pivotal bearing on the first frame member to rock on a longitudinal axis, kerf cutting mechanism including an elongated plane cutter bar carrying an orbitally movable cutter chain, said cutter chain being mounted on said second frame member and having angular movement with respect thereto, a motor mounted on said first frame member, mechanism driven by said motor for driving the cutter chain in any position of said bar including a shaft concentric with the pivotal bearing of said second frame member, said shaft being operatively connected with the cutter chain, mechanism driven by said motor for effecting angular movement of said bar at a cutting speed relative to said second frame member, and motor operated devices for effecting rectilinear movements of said cutter bar at a cutting speed to effect sumping and withdrawal cuts and for swinging said cutter bar at a cutting speed to effect a transverse cut.

130. In a mining machine, a wheeled support, a frame member having pivotal bearing on said support to rock on a transverse axis, a second frame member having pivotal bearing on the first frame member to rock on a longitudinal axis, kerf cutting mechanism

including an elongated plane cutter bar carrying an orbitally movable cutter chain, said cutter chain being mounted on said second frame member and having angular movement with respect thereto, a motor mounted on said first frame member, mechanism driven by said motor for driving the cutter chain in any position of said bar including a shaft concentric with the pivotal bearing of said second frame member, said shaft being operatively connected with the cutter chain, mechanism driven by said motor for rocking said second frame member about its axis at a bar positioning speed to change the plane of operation of the cutter bar, and motor operated devices for effecting rectilinear movements of said cutter bar at a cutting speed to effect sumping and withdrawal cuts and for swinging said cutter bar at a cutting speed to effect a transverse cut.

131. In a mining machine, a wheel supported frame member pivoted to rock on a transverse axis, a second frame member pivotally connected to the first frame member to rock on a longitudinal axis, kerf cutting mechanism mounted on said second frame member and having angular movement with respect thereto, said cutting mechanism including a pivoted elongated plane cutter bar carrying an orbitally movable cutter chain, motor operated devices for effecting swinging movement of said cutter bar at a cutting speed, and means for raising and lowering said cutting mechanism to change the plane of said cutter bar.

132. In a mining machine, a wheel supported frame member pivoted to rock on a transverse axis, a second frame member pivotally connected to the first frame member to rock on a longitudinal axis, kerf cutting mechanism mounted on said second frame member and having angular movement with respect thereto, said cutting mechanism including a pivoted elongated plane cutter bar carrying an orbitally movable cutter chain, and motor operated devices for raising and lowering said cutting mechanism at a bar positioning speed to change the plane of said cutter bar.

133. In a mining machine, a wheel supported frame member pivoted to rock on a transverse axis, a second frame member pivotally connected to the first frame member to rock on a longitudinal axis, kerf cutting mechanism mounted on said second frame member and having angular movement with respect thereto, said cutting mechanism including a pivoted elongated plane cutter bar carrying an orbitally movable cutter chain, motor operated devices for effecting swinging movement of said cutter bar at a cutting speed, and motor operated devices for raising and lowering said cutting mechanism at a bar positioning speed to change the plane of said cutter bar.

134. In a mining machine, a wheel support-

ed frame member pivoted to rock on a transverse axis, a second frame member pivotally connected to the first frame member to rock on a longitudinal axis, kerf cutting mechanism mounted on said second frame member 5 and having angular movement with respect thereto, said cutting mechanism including a pivoted elongated plane cutter bar carrying an orbitally movable cutter chain, motor operated devices for raising and lowering said cutting mechanism at a bar positioning speed to change the plane of said cutter bar, and motor operated devices for effecting rectilinear movements of said cutter bar at a cutting speed to make sumping and withdrawal cuts and for swinging said bar at a cutting speed to make a transverse cut.

135. In a mining machine, a wheel supported frame member pivoted to rock on a transverse axis, a second frame member 20 pivotally connected to the first frame member to rock on a longitudinal axis, kerf cutting mechanism mounted on said second frame member and having angular movement with respect thereto, said cutting mechanism including a pivoted elongated plane cutter bar carrying an orbitally movable cutter chain, motor operated devices for effecting swinging movement of said cutter bar at a cutting speed, motor operated devices for raising and lowering said cutting mechanism at a bar positioning speed to change the plane of said cutter bar, and motor operated devices for effecting rectilinear 25 movements of said cutter bar at a cutting speed to make sumping and withdrawal cuts and for swinging said bar at a cutting speed to make a transverse cut.

136. In a mining machine, a wheel supported frame member pivoted to rock on a transverse axis, a second frame member pivotally connected to the first frame member to rock on a longitudinal axis, kerf cutting mechanism mounted on said second frame member 40 and having angular movement with respect thereto, said cutting mechanism including a pivoted elongated plane cutter bar carrying an orbitally movable cutter chain, motor operated devices for raising and lowering said cutting mechanism at a bar positioning speed to change the plane of said cutter bar, and motor operated devices for rocking said first frame member about its axis to change the angle of said cutter bar relative 45 to the horizontal.

137. In a mining machine, a wheel supporting frame member pivoted to rock on a transverse axis, a second frame member pivotally connected to the first frame member to 55 rock on a longitudinal axis, kerf cutting mechanism mounted on said second frame member and having angular movement with respect thereto, said cutting mechanism including a pivoted elongated plane cutter bar carrying an orbitally movable cutter chain, 60

motor operated devices for effecting swinging movement of said cutter bar at a cutting speed, motor operated devices for raising and lowering said cutting mechanism at a bar positioning speed to change the plane of 70 said cutter bar, and motor operated devices for rocking said first frame member about its axis to change the angle of said cutter bar relative to the horizontal.

138. In a mining apparatus, a wheel mounted support adapted to run along a trackway, kerf cutting mechanism on said support including a pivoted elongated plane cutter bar carrying an orbitally movable cutter chain, motor operated devices for effecting bar swing at a cutting speed, means for adjusting said cutter bar into different planes relative to said support, and mechanism for tilting said support about a transverse axis to change the angle of said cutter bar relative to the horizontal. 75

139. In a mining apparatus, a wheel mounted support adapted to run along a trackway, kerf cutting mechanism on said support including a pivoted elongated plane 80 cutter bar carrying an orbitally movable cutter chain, motor operated devices for adjusting said bar at a bar positioning speed into different planes relative to said support, and mechanism for tilting said support about a transverse axis to change the angle of said cutter bar relative to the horizontal. 90

140. In a mining apparatus, a wheel mounted support adapted to run along a trackway, kerf cutting mechanism on said support including a pivoted elongated plane cutter bar carrying an orbitally movable cutter chain, motor operated devices for effecting bar swing at a cutting speed, motor operated devices for adjusting said bar at a bar 100 positioning speed into different planes relative to said support, and mechanism for tilting said support about a transverse axis to change the angle of said cutter bar relative to the horizontal. 105

141. In a mining apparatus, a wheel mounted support adapted to run along a trackway, kerf cutting mechanism on said support including a cutter carrying head rotatable on a longitudinal axis, an elongated plane cutter bar pivotally mounted on said head and carrying an orbitally movable cutter chain, motor operated devices for effecting bar swing at a cutting speed, means for adjusting said bar into different planes, and mechanism for tilting said cutting mechanism about a transverse axis to change the angle of the cutter bar relative to the horizontal. 110

142. In a mining apparatus, a wheel 125 mounted support adapted to run along a trackway, kerf cutting mechanism on said support including a cutter carrying head rotatable on a longitudinal axis, an elongated plane cutter bar pivotally mounted on said 130

head and carrying an orbitally movable cutter chain, motor operated devices for adjusting said cutter bar at a bar positioning speed into different planes, and mechanism for tilting said cutting mechanism about a transverse axis to change the angle of the cutter bar relative to the horizontal.

143. In a mining apparatus, a wheel mounted adapted to run along a trackway, kerf cutting mechanism on said support including a cutter carrying head rotatable on a longitudinal axis, an elongated plane cutter bar pivotally mounted on said head and carrying an orbitally movable cutter chain, motor operated devices for effecting bar swing at a cutting speed, motor operated devices for adjusting said cutter bar at a bar positioning speed into different planes, and mechanism for tilting said cutting mechanism about a transverse axis to change the angle of the cutter bar relative to the horizontal.

144. In a mining apparatus, a wheel mounted support adapted to run along a trackway, a frame on said support, cutting mechanism including a cutter carrying head mounted on said frame for rotation about a longitudinal axis, said cutting mechanism also including an elongated plane cutter bar carrying an orbitally movable cutter chain and suitably mounted on said head for swinging movement relative thereto, a motor on said support, mechanism driven by said motor for rotating said head about its axis and for swinging said cutter bar about its pivot at a cutting speed, mechanism driven by said motor for actuating the cutter chain, and mechanism for tilting said cutter bar relative to said support to change the angle of said bar relative to the horizontal.

145. In a mining machine, a wheeled truck, a motor carried thereby, cutting mechanism on said truck including a cutter carrying head rotatable between horizontal and vertical cutting positions about a horizontal longitudinally extending axis, and an elongated plane cutter bar carrying an orbitally movable cutter chain pivotally mounted on said head for swinging movement relative thereto, mechanism driven by said motor for actuating the cutter chain, and mechanism driven by said motor for swinging said cutter bar about its pivot at a cutting speed in any position of said head about its axis.

146. In a mining machine, a wheeled truck, a motor carried thereby, cutting mechanism on said truck including a cutter carrying head rotatable between horizontal and vertical cutting positions about a horizontal longitudinally extending axis, and an elongated plane cutter bar carrying an orbitally movable cutter chain pivotally mounted on said head for swinging movement relative thereto, mechanism driven by said motor

for actuating the cutter chain, mechanism driven by said motor for rotating said head about its axis at a bar positioning speed to move said bar bodily about the head axis to change the plane of operation of said bar, and mechanism driven by said motor for swinging said cutter bar about its pivot at a cutting speed in any position of said head about its axis.

147. In a mining machine, a wheeled truck, a motor carried thereby, cutting mechanism on said truck including a cutter carrying head rotatable between horizontal and vertical cutting positions about a horizontal longitudinally extending axis, and an elongated plane cutter bar carrying an orbitally movable cutter chain pivotally mounted on said head for swinging movement relative thereto, mechanism driven by said motor for actuating the cutter chain, mechanism driven by said motor for rotating said head about its axis at a bar positioning speed to move said bar bodily about the head axis to change the plane of operation of said bar, mechanism driven by said motor for swinging said cutter bar about its pivot at a cutting speed in any position of said head about its axis, and motor driven mechanism for tilting said cutting mechanism about a transverse axis to change the angle of the cutter bar relative to the horizontal.

148. In a mining machine, a wheeled truck, a swivel member mounted thereon rotatable about a vertical axis, a motor carried by said swivel member, kerf cutting mechanism on said swivel member including a cutter carrying head rotatable relative to said swivel member about a horizontal longitudinally extending axis and an elongated plane cutter bar carrying an orbitally movable cutter chain pivotally mounted on said head for swinging movement relative thereto, mechanism driven by said motor for actuating the cutter chain, and mechanism driven by said motor for swinging said cutter bar about its pivot at a cutting speed in any position of said head about its axis.

149. In a mining machine, a wheeled truck, a swivel member mounted thereon rotatable about a vertical axis, a motor carried by said swivel member, cutting mechanism on said swivel member including a cutter carrying head rotatable about a horizontal longitudinally extending axis and an elongated plane cutter bar carrying an orbitally movable cutter chain pivotally mounted on said head for swinging movement relative thereto, mechanism driven by said motor for actuating the cutter chain, mechanism driven by said motor for rotating said head about its axis at a bar positioning speed to move said bar bodily about the head axis to change the plane of operation of said bar, and mechanism driven by said motor for swinging said cutter bar

about its pivot at a cutting speed in any position of said head about its axis.

150. In a mining machine, a wheeled truck, a swivel thereon rotatable about a vertical axis, a horizontal guideway wholly supported by said truck and mounted on said swivel for horizontal adjustment about the swivel axis to positions respectively parallel to or at right angles to the central longitudinal line of the truck, a mining mechanism mounted on said guideway for movement therealong during cutting and including a motor and kerf cutting mechanism driven by said motor including an elongated horizontal plane cutter bar carrying an orbitally movable cutter chain, and mechanism driven by said motor for actuating said cutter chain and for moving said mining mechanism bodily relative to said guideway at a cutting speed to cut a horizontal kerf.

151. In a mining apparatus, in combination, a track, a wheeled truck movable thereon, a support swiveled on a fixed vertical axis on said truck and wholly supported thereby, a motor driven cutting mechanism carried on said support and including a cutter bar movable to cut in horizontal and vertical planes, and means disposed in rear of said support and operative in different positions of said cutting mechanism whereby movement of said truck and said bar relative to the latter may be had, said means including a common actuating element.

152. In combination, a mining machine truck, swiveled kerf cutting mechanism thereon including a cutter bar and a cutter chain thereon, means for tilting said mechanism relative to said truck to permit cutting of plane kerfs in angularly related planes including a swivel carrying support movable about a horizontally disposed pivot and cooperating adjusting means, and self-contained means for moving said kerf cutting and tilting means longitudinally of said truck.

153. In combination, a mining machine truck, a support non-rotatably carried thereon but movable longitudinally therealong, a cooperating support pivoted on said support on a longitudinal axis, means for adjusting said cooperating support about its axis in either direction from the horizontal, and kerf cutting mechanism on said cooperating support.

154. In a mining machine, a support, cutting mechanism carried by said support and including a swinging cutter bar, means for moving said bar to different planes respectively at angles to each other including a plurality of means for changing the plane of cut of said cutter bar, power means for actuating the same, each operative independently of the other and respectively moving the bar in different paths, power actuated means for swinging said cutter bar, power actuated means for feeding said cutter bar,

and a common source of power for certain of said power actuated means.

155. In a mining apparatus, the combination with a truck movable on a trackway and an elongated horizontal guiding means on said truck, of vertical kerf cutting mechanism pivotally mounted on said truck and including a cutter bar having a cutter chain adapted to cut a kerf for said bar in a face when said bar is presented edgewise thereto, a motor, mechanism driven by said motor for actuating said cutter chain, and self-contained means driven by said motor for moving said cutter mechanism along said guiding means between the ends thereof to effect movement of said cutter bar bodily rectilinearly thereof, about its pivot vertically in the same plane, and reversely rectilinearly relative to said guiding means to insert a vertical kerf in a face in front of the end of the trackway.

156. In a mining apparatus, the combination with a wheeled truck movable on a trackway and an elongated horizontal guiding means on said truck, of vertical kerf cutter mechanism pivotally mounted thereon and including a cutter chain carrying cutter bar disposable in fixed relation at acute angles to said guiding means above and below the latter, a motor, driving connections between said motor and said cutter chain, and self-contained means driven by said motor and supported on said truck for moving said cutter bar when so disposed along said guiding means rectilinearly relative thereto between the ends thereof, relatively vertically downward in its plane, and reversely rectilinearly to form a vertical kerf substantially equal to the length of said cutter bar and in a face in front of the end of the trackway.

157. In a mining apparatus, the combination with a wheeled truck movable on a trackway and an elongated horizontal guiding means on said truck, of vertical kerf cutter mechanism pivotally mounted thereon and including a cutter chain carrying cutter bar disposable in fixed relation at acute angles to said guiding means above and below the latter, self-contained power operated means supported on said truck for moving said cutter bar when so disposed along said guiding means rectilinearly relative thereto between the ends thereof, relatively vertically downward in its plane, and reversely rectilinearly to form a vertical kerf substantially equal to the length of said bar and in a face in front of the trackway, and self-contained power operated means on the truck for driving the truck wheels to propel the apparatus along the trackway.

158. In a mining apparatus, the combination with a truck movable on a trackway and an elongated horizontal guiding means on said truck, of vertical kerf cutter mechanism pivotally mounted on said truck and comprising a cutter bar having a cutter chain

adapted to cut a kerf for said bar in a face when said bar is presented edgewise thereto, self-contained power operated means for moving the cutter mechanism along said guiding means between the ends thereof to effect movement of said cutter bar bodily rectilinearly relative thereto, about its pivot vertically in the same plane, and reversely rectilinearly of said guiding means to insert a vertical kerf in a face in front of the end of the trackway, and self-contained power operated means on the truck for driving the truck wheels to propel the apparatus along the trackway.

159. In a mining apparatus, the combination with a truck movable on a trackway, of cutter mechanism pivotally mounted on said truck and including a cutter bar having a cutter chain adapted to cut a kerf for said bar in a face when said bar is presented edgewise thereto, a horizontal motor on said truck having its power shaft extending longitudinally of the apparatus, driving connections between one end of said power shaft and said cutter chain, and self-contained power operated means for moving the cutter mechanism relative to the trackway to effect movement of said cutter bar bodily rectilinearly of the trackway at a cutting speed, about its pivot in the same plane, and reversely rectilinearly of the trackway at a cutting speed to insert a kerf in a face in front of the end of the trackway, said self-contained means including bar swinging means and means for effecting the rectilinear movements of the bar and at a cutting speed, driving connections between the same end of said motor and said bar swinging means, and driving connections between the opposite end of said power shaft and said bar moving means including a toothed power transmission element mounted on said opposite end of said power shaft.

160. In a mining apparatus, the combination with a truck movable on a trackway, of cutter mechanism pivotally mounted on said truck and including a cutter bar having a cutter chain adapted to cut a kerf for said bar in a face when said bar is presented edgewise thereto, a horizontal motor on said truck having its power shaft extending longitudinally of the apparatus, driving connections between the front end of said power shaft and said cutter chain, and self-contained power operated means for moving the cutter mechanism relative to the trackway to effect movement of said cutter bar bodily rectilinearly of the trackway at a cutting speed, about its pivot in the same plane, and reversely rectilinearly of the trackway at a cutting speed to insert a kerf in a face in front of the end of the trackway, said self-contained means including bar swinging means and means for effecting the rectilinear movements of the bar and at a cutting speed, driving connections

between the front end of said power shaft and said bar swinging means, and driving connections between the rear end of said power shaft and said bar moving means, including a toothed power transmission element mounted on the rear end of said power shaft.

161. In a mining machine, a support, cutting mechanism carried by said support and including a swinging cutter bar, a plurality of means for changing the plane of cut of said cutter bar respectively operative to move said bar to angularly disposed planes and into different parallel planes, power means for actuating the same, power actuated means for swinging said cutter bar, and power actuated mechanism for feeding said cutter bar.

162. In a mining machine, a frame movable on a trackway and having longitudinally disposed guiding means thereon, and cutting mechanism movable longitudinally of said means and operative to cut a kerf beginning practically immediately at the front of the same and including an independently pivoted cutter chain carrying swinging cutter bar having its plane of operation disposable above or below said guiding means.

163. In a mining apparatus, a frame movable longitudinally during cutting and including a motor disposed longitudinally of said frame and a swivel head, a cutter bar pivotally mounted on said swivel head for swinging movement about an axis perpendicular to the axis of rotation of said swivel head, means extending through said swivel head for actuating said cutter bar and for effecting swinging movement thereof by power from said motor, power driven means for rotating said swivel head, and means driven from the end of said motor remote from said swivel head for effecting feeding of said apparatus.

164. In a mining apparatus, a wheel mounted support adapted to run along a trackway, kerf cutting mechanism on said support including a pivoted elongated plane cutter bar carrying an orbitally movable cutter chain, motor operated devices for adjusting said cutter bar at a bar positioning speed into different parallel horizontal planes relative to said support, and mechanism for tilting said support about a transverse axis to change the angle of said cutter bar relative to the horizontal.

165. In a mining apparatus, a wheel mounted support adapted to run along a trackway, kerf cutting mechanism on said support including a pivoted elongated plane cutter bar carrying an orbitally movable cutter chain, motor operated devices for effecting bar swing at a cutting speed, motor operated devices for adjusting said cutter bar at a bar positioning speed into different parallel horizontal planes relative to said support, and mechanism for tilting said support about a transverse axis to change the angle of said cutter bar relative to the horizontal.

166. In a mining apparatus, a wheel mounted support adapted to run along a trackway, kerf cutting mechanism on said support including a pivoted elongated horizontal plane cutter bar swingable in horizontal planes to cut horizontal kerfs and carrying an orbitally movable cutter chain, and motor operated devices for effecting bar swing at a cutting speed, motor operated devices for adjusting said bar at a bar positioning speed into different parallel horizontal planes relative to said support, and mechanism for tilting said cutter bar about a transverse axis to change the angle of said cutter bar relative to the horizontal.

167. In a mining machine, a wheel supported frame member pivoted to rock on a transverse axis, a second frame member pivotally connected to the first frame member to rock on a longitudinal axis, kerf cutting mechanism mounted on said second frame member and having angular movement with respect thereto, said cutting mechanism including a pivoted elongated plane cutter bar carrying an orbitally movable cutter chain, and means for raising and lowering said cutter bar into different parallel planes.

168. In a mining machine, a wheel supported frame member pivoted to rock on a transverse axis, a second frame member pivotally connected to the first frame member to rock on a longitudinal axis, kerf cutting mechanism mounted on said second frame member and having angular movement with respect thereto, said cutting mechanism including a pivoted elongated plane cutter bar carrying an orbitally movable cutter chain, and motor operated devices for raising and lowering said cutter bar at a bar positioning speed into different parallel planes.

169. In a mining machine, a wheel supported frame member pivoted to rock on a transverse axis, a second frame member pivotally connected to the first frame member to rock on a longitudinal axis, kerf cutting mechanism mounted on said second frame member and having angular movement with respect thereto, said cutting mechanism including a pivoted elongated plane cutter bar carrying an orbitally movable cutter chain, motor operated devices for effecting bar swing at a cutting speed, and motor operated devices for raising and lowering said cutter bar at a bar positioning speed into different parallel planes.

170. In a mining machine, a wheel supported frame member pivoted to rock on a transverse axis, a second frame member pivotally connected to the first frame member at the front end thereof to rock on a longitudinal axis, a support mounted on said second frame member and having angular movement with respect thereto, kerf cutting

mechanism mounted on said support including a pivoted elongated plane cutter bar carrying an orbitally movable cutter chain, and motor operated devices for raising and lowering said cutter bar at a bar positioning speed into different parallel planes above and below the axis of said second frame member.

171. In a mining machine, a wheel supported frame member pivoted to rock on a transverse axis, a second frame member pivotally connected to the first frame member at the front end thereof to rock on a longitudinal axis, a support mounted on said second frame member and having angular movement with respect thereto, kerf cutting mechanism mounted on said support including a pivoted elongated plane cutter bar carrying an orbitally movable cutter chain, motor operated devices for effecting bar swing at a cutting speed, and motor operated devices for raising and lowering said cutter bar at a bar positioning speed into different parallel planes above and below the axis of said second frame member.

172. In a mining machine, a wheel supported frame member pivoted to rock on a transverse axis, a second frame member pivotally connected to the first frame member to rock on a longitudinal axis, kerf cutting mechanism mounted on said second frame member and having angular movement with respect thereto, said cutting mechanism including a pivoted elongated plane cutter bar carrying an orbitally movable cutter chain, means for raising and lowering said cutter bar into different parallel planes above and below the axis of the second frame member, and motor driven mechanism operative to effect forward and rearward rectilinear movements of said cutter bar at a cutting speed.

173. In a mining machine, a wheel supported frame pivoted to rock on a transverse axis, a second frame member pivotally connected to the first frame member to rock on a longitudinal axis, kerf cutting mechanism mounted on said second frame member and having angular movement with respect thereto, said cutting mechanism including a pivoted elongated plane cutter bar carrying an orbitally movable cutter chain, and motor operated devices for raising and lowering the cutter bar at a bar positioning speed into different parallel planes above and below the axis of the second frame member.

174. In a mining machine, a wheel supported frame member pivoted to rock on a transverse axis, a second frame member pivotally connected to the first frame member to rock on a longitudinal axis, kerf cutting mechanism mounted on said second frame member and having angular movement with respect thereto, said cutting mech-

- anism including a pivoted elongated plane cutter bar carrying an orbitally movable cutter chain, motor operated devices for raising and lowering the cutter bar at a bar positioning speed into different parallel planes above and below the axis of the second frame member, and motor driven mechanism operative to effect forward and rearward rectilinear movements of said cutter bar at a cutting speed.
175. In a mining machine, a wheel mounted support adapted to run along a trackway, kerf cutting mechanism on said support including a cutter carrying head rotatable on a longitudinal axis, an elongated plane cutter bar pivotally mounted on said head and carrying an orbitally movable cutter chain, motor operated devices for effecting bar swing at a cutting speed, motor operated devices for adjusting said cutter bar at a bar positioning speed into different parallel planes above and below the axis of head rotation, and mechanism for tilting said cutting mechanism about a transverse axis to change the angle of said cutter bar relative to the horizontal.
176. In a mining apparatus, a wheel mounted support adapted to run along a trackway, a motor on said support, kerf cutting mechanism on said support including a cutter carrying head rotatable on a longitudinal axis, an elongated plane cutter bar pivotally mounted on said head and carrying an orbitally movable cutter chain, mechanism driven by said motor for effecting bar swing at a cutting speed, mechanism driven by said motor for adjusting said cutter bar at a bar positioning speed into different parallel horizontal planes above and below the axis of head rotation, and mechanism for tilting said cutting mechanism about a transverse axis to change the angle of said cutter bar relative to the horizontal.
177. In a mining apparatus, a wheel mounted support adapted to run along a trackway, a motor on said support, kerf cutting mechanism on said support including a cutter carrying head rotatable on a longitudinal axis, an elongated plane cutter bar pivotally mounted on said head and carrying an orbitally movable cutter chain, mechanism driven by said motor for effecting bar swing at a cutting speed, mechanism driven by said motor for adjusting said cutter bar at a bar positioning speed into different parallel horizontal planes above and below the axis of head rotation, mechanism for tilting said cutting mechanism about a transverse axis to change the angle of said cutter bar relative to the horizontal, and mechanism driven by said motor for effecting forward and rearward rectilinear movements of said cutter bar at a cutting speed.
178. In a mining machine, a wheeled truck adapted to run along a trackway, a body
- thereon, a motor in said body, kerf cutting mechanism including a cutter carrying head rotatably mounted on the forward end of said body for rotation about a longitudinal axis and a pivoted elongated plane cutter bar carrying an orbitally movable cutter chain mounted on said head, mechanism driven by said motor for actuating the cutter chain and for swinging said bar about its pivot at a cutting speed, mechanism driven by said motor for rotating said head about its axis to move said bar into different parallel planes above and below the head axis, and mechanism driven by said motor for effecting rectilinear movements of said cutter bar at a cutting speed to make sumping and withdrawal cuts.
179. In a mining machine, a wheeled truck adapted to run along a trackway, a body thereon, a motor in said body having its power shaft extending longitudinally of the machine, kerf cutting mechanism including a cutter carrying head rotatably mounted on the forward end of said body for rotation about a longitudinal axis, mechanism for rotating said head about its axis to move said cutter bar into different parallel planes above and below the head axis, mechanism driven from one end of said motor for actuating the cutter chain, and mechanism driven from the opposite end of said motor for effecting rectilinear movements of the cutter bar at a cutting speed to make sumping and withdrawal cuts.
180. In a mining machine, a wheeled truck adapted to run along a trackway, a body thereon, a motor in said body having its power shaft extending longitudinally of the machine, kerf cutting mechanism including a cutter carrying head rotatably mounted on the forward end of said body for rotation about a longitudinal axis, mechanism for rotating said head about its axis to move said cutter bar into different parallel planes above and below the head axis, mechanism driven from the front end of said motor for actuating the cutter chain, and mechanism driven from the rear end of said motor for effecting rectilinear movements of the cutter bar at a cutting speed to make sumping and withdrawal cuts.
- In testimony whereof I affix my signature.
- FRANK CARTLIDGE.
